AUTOMATIC GRINDING MACHINE

John M. Morgan, Jr., Cincinnati, and Robert G. Wise, Loveland, Ohio, assignors to The Cincinnati Milling Machine Co., Cincinnati, Ohio, a corporation of Ohio

Filed Sept. 1, 1960, Ser. No. 53,533

42 Claims. (Cl. 51—165)

This invention relates to an automatic machine tool control mechanism and is particularly suitable for a precision grinding machine.

Numerical control of machine tools, in which previously prepared operating data is stored in some medium such as tape for presentation to the machine when required, has come to be recognized as a useful implement for economical production in some circumstances. All machine tool applications are not economically adapted for numerical control, however, and the automatic cycle as well as the hand machining cycle still have their places as important and economical modes of machine tool operation. Since this is true, a machine control mechanism which is versatile enough to allow for both automatic and hand cycle modes of operation, but which is readily adapted for numerical control, is particularly valuable. The control system becomes even more significant if it gives a degree of accuracy that is acceptable in precision grinding operations which have traditionally required more accuracy than most other metal working operations.

A grinding machine combined with a control mechanism constructed in accordance with the preferred form of this invention has control stations from which operation of the machine slides, that is, the wheelhead and the table, are controlled. There is no mechanical connection between the control stations and the slides but, instead, the slide motors are controlled by electrical signals emanating from the control stations. Thus many difficult alignment problems are avoided and the control stations may be placed in accordance with principles of convenience since their location is not influenced by mechanical limitations.

The wheelhead control station includes a wheelhead handwheel, the rotation of which produces an electrical signal which controls the wheelhead motor, and hence movement of the wheelhead. The handwheel may be manually rotated, for manual control of wheelhead movement, or may be rotated by a control motor included in the control station so that the wheelhead follows the control motor in automatic grinding cycles. The control motor and the handwheel are small members, remote from any heat generated by the operation, which simulate, in the control station, the wheelhead motor and the wheelhead in the machine, and the handwheel, which is isolated from the mass of the wheelhead and can therefore be stopped with more accuracy than the wheelhead or a member connected thereto, is driven to a positive stop by the control motor so that a wheelhead moving signal can be repeatedly reproduced for accurate control of the wheelhead in grinding cycles. Complete information to move the wheelhead through a selected predetermined grind cycle is stored in the control station and is utilized to direct a predetermined operation of the control motor in which the handwheel is driven against the positive stop to repeatedly terminate the infeed at precisely the same predetermined distance from the position from which the grind cycle started.

The basic electrical control of the wheelhead motor by the handwheel and control motor through which manual control of wheelhead positioning and a manual or automatic grinding cycle is effected lends itself readily to the superposition of a signal for the automatic positioning

2

of the wheelhead, as for a grinding cycle. To this end a wheelhead position control motor is provided which, like the control motor, is mechanically isolated from the machine. The operation of the wheelhead position control motor modifies the signal supplied to the wheelhead motor so that the wheelhead motor will follow the operation of the wheelhead position control motor as it follows the wheelhead control motor. The operation of the wheelhead position control motor is determined by a signal originating from a position information storage mechanism, which signal may be established by manually set dials or by a portion of a tape. Thus the position information is added into the operation of the wheelhead without affecting the automatic grinding cycle set in the wheelhead control station.

Other wheelhead control functions may be superimposed on the basic electric control of the wheelhead motor in a similar manner. The mechanisms provided for performing these functions cause operation of the wheelhead motor and do not affect the other portions of the wheelhead control mechanism. Thus, correction control signals may be added to the flow of signal information to the wheelhead motor. These correction signals are used to produce components of wheelhead movement that correct for predetermined inaccuracies in the drive mechanism between the wheelhead and the wheelhead motor. A grinding wheel attrition compensation signal is also produced and added in as a part of the sum of wheelhead control information. This compensation signal causes the wheelhead to move to adjust for reduction of the grinding wheel diameter at each truing operation and modifies all subsequent signals to the wheelhead motor to compensate for previous attrition of the grinding wheel.

The work supporting table has a table motor by which it is moved. The table motor is controlled by electrical signals which are produced in a table control station. The table control signals may be produced by operation of a table handwheel, in the control station, or may be produced through the operation of a table control motor. The table control motor and table handwheel both lead the table motor. The operation of the table control motor may be controlled by a reversing lever and hand-set table dogs or by the information storage mechanism. The storage mechanism directs operation of the table control motor to move the table to a predetermined position prior to a grinding cycle. The storage mechanism also provides signals to direct the table control motor to lead the table motor in an alternating operation which causes the table to be reciprocated between two preselected positions. Thus the table may be automatically positioned for plunge grinding and automatically reciprocated for traverse grinding and wheel truing.

Switching circuits of the mechanism combine the functions of the wheelhead and table to coordinate their movements during automatic operation of the machine. These circuits also coordinate the operation of the wheelhead and table motors with the operation of a fixed stroke rapid advance motor which is utilized to effect clearance between the grinding wheel and a workpiece between grinding operations to allow for table movement and change of workpieces without damage thereto.

It is therefore an object of this invention to provide a versatile machine tool control mechanism that is readily adapted to all types of manual and automatic cycle operation including numerical control.

It is a further object to provide control mechanism which is accurate enough for use in precision grinding operations.

Still another object is to provide a control mechanism which is relatively unaffected by heat generated by the operation and eliminates most of the drive system fitting

and alignment procedures required in a grinding machine which has a mechanical feed system with a lead screw and mechanically linked handwheel mechanism.

It is yet another object of the present invention to provide a grinding machine capable of automatically performing a plurality of grinds on a single multi-diameter workpiece, said grinds being plunge or traverse in any desired sequence.

Other objects and advantages of the present invention should be readily apparent by reference to the following specification, considered in conjunction with the accompanying drawings forming a part thereof, and it is to be understood that any modifications may be made in the exact structural details there shown and described, within the scope of the appended claims, without departing from or exceeding the spirit of the invention.

The following detailed description will give a full understanding of the construction and operation of this invention. Reference will be made to the attached drawings in which:

FIG. 1 is a front elevation of a grinding machine.

FIG. 2 is a block diagram of the components of the grinding machine table control mechanism.

FIG. 3 is a simplified diagram of the mechanical and electrical linkages in the table control mechanism.

FIG. 4 is a simplified section of the grinding machine wheelhead.

FIG. 5 is a section of FIG. 4 on line 5—5.

FIG. 6 is a block diagram of the components of the grinding machine wheelhead control mechanism.

FIG. 7A is a development of the feed cycle control mechanism of the grinding machine.

FIG. 7B is a section of FIG. 7A taken on line 7B—7B.

FIG. 10 is an elevation of the wheelhead compensation unit in FIG. 8 as it is mounted on the grinding machine.

FIGS. 11A through 11H show the control relay circuit of the grinding machine.

FIGS. 12A through 12C show the circuit of the master stepping switch in the grinding machine control mechanism.

FIGS. 13A through 13C show the electrical and mechanical connections between the components of the table control mechanism.

FIGS. 14A through 14C show the electrical and mechanical connections between the components of the wheelhead control mechanism.

FIG. 15 is the table and wheelhead hydraulic circuit for the grinding machine.

The Table Mechanism

In the machine described, a worktable 12 (FIGS. 1 and 3) is slidably received on ways 14 in the machine base 92 and is reciprocally movable, parallel to an X axis, in the longitudinal direction by operation of a table motor TM connected thereto. The table has a headstock 13 and a tailstock 15 mounted thereon with centers 16 adapted to receive and hold a workpiece 17. A rotating grinding wheel 18 is supported in a wheelhead member 19 slidably received on cross slide ways 20 (FIG. 4) for movement, parallel to a Y axis perpendicular to the X axis, into abrasive contact with the workpiece. As shown in FIG. 1, the workpiece 17 may have a plurality of portions having different diameters, some of which, such as 17a and 17b are longer than the width of the wheel and require a traverse grinding operation to finish. Others such as 17c and 17d are shorter and may be plunge ground. The table also carries a grinding wheel dressing tool 22, mounted on the tailstock 15, for use in truing and dressing of the grinding wheel between grinding operations. In plunge grinding portions 17c and 17d the table is moved to a predetermined position prior to the grinding cycle, and then held stationary while the wheel is moved into abrasive contact with the workpiece. For traverse grind-

ing of portions 17a and 17b, and for wheel truing operations, the table is moved first to a predetermined starting position and then reciprocated until the operation is complete, the grinding wheel being moved into the workpiece, or truing tool, in steps coordinated with the table strokes. All movement of the table is effected by the operation of the table motor.

The table motor TM (FIG. 3) is a rotary hydraulic motor which is operatively connected to the table 12 through a gear train 34 terminating in a pinion 26 and a rack 24 connected to the table. The table motor is hydraulically connected to a hydraulic servo valve 28 which operates to complete a fluid path from a source of fluid under pressure through the table motor TM to a fluid reservoir. The servo valve is electrically connected through an amplifier 32 to a table synchro receiver 30 for operation when a signal appears at the synchro receiver. The synchro receiver, or synchro control transformer, 30 is a part of a synchro device of the resolver type, constituting a signal generator, including a pair of synchro transmitters 36 and 90 (see FIGS. 2, 3, 13c) relying on magnetic coupling for producing, or generating, an error signal at the synchro receiver. The synchro transmitter 36 and receiver 30 each have a pair of stator windings (36S and 30S, respectively) electrically ninety degrees apart. Each also has a rotor winding, or armature, (36R, 30R) rotatable relative to the stator windings. The synchro transmitter 90 is connected in series with transmitter 36 and receiver 30, the pair of stator windings 90S being connected to transmitter rotor windings 36R and the rotor windings 90R, or armature, being connected to receiver stator windings 30S. One transmitter stator winding 36S is connected to a source OSC (FIG. 11A) of 400 cycle voltage (the other stator winding 36S of this transmitter is shorted) and the receiver rotor 30R is connected to amplifier 32. Thus a signal produced in transmitter 36, on rotation of rotors 36R to a predetermined angular position relative to stator windings 36S, produces, for any given position of the rotor windings of transmitter 90, a predetermined error signal in the synchro receiver 30 which is amplified in amplifier 32 and transmitted to servo-valve 28. The motor TM is mechanically connected through gear train 31 to rotors 30R and the motor is run by the signal in the servo-valve 28 in an error signal reducing direction so that the motor stops (to position the table in a predetermined position) when the receiver rotor windings have been rotated to a position where the error signal nulls. If the position of the rotor windings of transmitter 90 are angularly adjusted, an adjusted error signal will be produced in receiver rotor winding 30R, and the table will be positioned in a correspondingly adjusted position. Thus the total output of the transmitters is the sum of the angular positions of the rotor windings thereof and this sum represents a single angular position of the rotor winding of the receiver where the error signal voltage nulls. When one of the transmitter rotors is changed, the sum is changed and an error signal is produced at the synchro receiver until its rotor windings are rotated to correspond to the position of the resulting sum of the transmitters. It will be understood that the transmitter rotors may be rotated through many revolutions before being stopped in a predetermined angular position and that the table motor will rotate the receiver rotor to follow the revolutions of the transmitter rotors to a final position defined by the final position of the transmitter rotors. Thus the total movement of the table will be determined by the total rotations of the transmitter rotors.

A table control motor TCM is mechanically connected through reduction gearing 40 to rotate the rotor windings 36R of the table synchro transmitter 36. The motor TCM is a two phase variable speed electric motor, stabilized by tachometer 42, and is energized either by a position command signal emanating from an electronic unit 70 (see FIG. 2) or by a rate command signal emanating from

switcher unit 52. One or the other of electronic unit 70 and switcher 52 is connected, through either normally open or normally closed contacts of relay 17BCR to table control motor amplifier 44 which, in turn, is connected to the table control motor TCM. The rate command signal from switching unit 52 is used to direct table movement when the table is in a conventionally controlled cycle of operation. Such a cycle would be used during a manual or table dog controlled traverse grinding or truing operation. A constant but adjustable voltage is developed across a rate potentiometer 46 (FIG. 13B) connected to the secondary of transformer 33 of unit 52 and is utilized as a rate control signal which determines the rate at which the table control motor operates. The direction of rotation is determined by the phase at which the signal is applied in the control motor circuit. A change in phase is effected by operation of the table reversing lever 50 (FIG. 3). The table reversing lever opens one limit switch 106LS and closes another 107LS when its position is changed to energize one control relay 15CR and de-energize another 14CR to effect the change of phase by reversing connections of the transformer 33 through contacts of these relays in the table switcher unit 52 (FIGS. 2, 3). The position of the reversing lever 50 (FIG. 3) may be changed by the machine operator or by contact with adjustable table dogs 54 as the table is moved.

In numerically controlled operation of the table, the output of unit 70 (FIG. 3) replaces the output of the table switching unit 52. A discrete portion 61a of a punched tape 61 or similar information storing medium operates in conjunction with a reader 59 and one or the other of a set (58, 60) of stepping switches to produce a position command signal which may be either an operating command signal for grinding cycles, or a truing command signal for the truing cycles. The position command signal comprises a sine and cosine component applied to the stator windings 62S, 64S, and 66S of a set of table position error synchros which comprise a coarse synchro 62, a medium synchro 64, and a fine synchro 66, each synchro being of the resolver type. The sine and cosine components of the command signal define a unique angular position of the rotor windings at which the output therefrom will null. When the position command signal is applied to these position error synchros, an electrical output signal is produced across the rotor windings 62R, 64R, 66R. The rotor windings of synchros 62, 64, 66 are connected to an electronic synchronizing network included in a three channel amplifier 68. This network (which may be any suitable well known synchronizing network) connects the output signals from the synchros 62, 64, 66 in sequence to the electronic unit 70 comprising an amplifier 72, a phase detector 74 which converts the signal from 400 cycle A.C. to a D.C. signal, and a modulator 76 which modulates a 60 cycle A.C. carrier current with the phase detector D.C. output. The modulated signal produced by the modulator portion 76 of the electronic unit 70 is applied through control motor amplifier 44 to the 60 cycle A.C. two phase table control motor TCM. The maximum magnitude of the signal from the modulator is determined by the setting of rate potentiometers included in the bias circuit 78 for the phase detector portion 74. A selected rate potentiometer is connected in the bias circuit through contacts of one of the relays 55CR, 56CR and 57CR (see FIG. 13B), there being separate rate potentiometers for traverse grinding 3POT, coarse truing 5POT, and fine truing 4POT. The table control motor amplifier 44 beefs up the output from the modulator to provide a signal sufficient to operate the table control motor TCM. The rate of operation depends on the magnitude of the signal from the table control motor amplifier 44 which is directly related to the magnitude of the signal from the modulator 76. The direction of operation of the table control motor is determined by the phase of the output from the table control motor amplifier 44. In numerically controlled operation, the

phase is determined by the position command signal introduced into the table position error synchros 62, 64, 66.

The rotor windings 62R, 64R and 66R of the position error synchros 62, 64, 66 (see FIG. 13A) are mechanically connected through gear train 65 (which may contain gears common to gear train 31 but which is indicated on FIGS. 2 and 13C separate therefrom for clarity) for rotation with the table control motor TCM. The table control motor is energized to rotate in a direction tending to reduce the output signal from the effective position error synchro. Therefore, for any input to the table position error synchro, the table control motor will be operated until the output from the position error synchro is nulled. The table motor TM follows operation of the table control motor TCM and moves the table while the table control motor is running. The table position command signal is determined by and related to the distance from a reference position to the position to which the table is to be moved. As long as the table is not in the commanded position there will be an output from the position error synchro proportional to the difference between actual position and command position. The output signal is effective to produce enough rotation of the control motor TCM to lead the table motor TM through sufficient rotation to correctly position the table relative to the reference position.

If the selected machine operation is for a plunge grind, the table is positioned and the grinding cycle would begin and run to completion before the table would move again. In the plunge grind operation, the table needs only one position command signal. However, if either traverse grinding or truing is to be performed automatically, two command signals have to be used, one corresponding to a position at one end of a table stroke, and the other corresponding to a position at the other end of the table stroke. Operation of a relay 54CR of the machine controls the connection of a command signal from one set of stepping switches 58 or another set 60 to the position error synchros 62, 64, 66 in the traverse and truing operations. These two command signals are produced in the table position storage mechanism (comprising the tape 61, reader 59, and the sets of stepping switches 58, 60) from a single discrete block of holes on the tape portion 61a in conjunction with the reader 59 and the sets of stepping switches 58, 60 to produce two command signals which are alternately applied to the position error synchros 62, 64, 66. For any command signal supplied to the position error synchros, the synchro will produce a voltage output of magnitude depending on the angular position of the synchro rotor windings (62R, 64R, 66R) relative to the angular position defined by the command signal, the angular position of the rotor windings being determined by the instantaneous position of the table. The voltage output from the synchros will produce a proportional voltage output at modulator 76 of a phase to drive the table in an error signal reducing direction until the voltage output of the position error synchros nulls. Thus any predetermined command signal input to the position error synchros corresponds to a predetermined table position. The phase of the voltage output at modulator 76 (and hence the direction in which the table will be moved by this voltage output) depends on the direction of the table at an instant relative to the predetermined position corresponding to the command signal, and the table can thus be reciprocated between the positions corresponding to the command signals supplied from the respective sets of stepping switches 58, 60 by alternately energizing and deenergizing relay 54CR, the normally closed and normally open contacts of which are in the lines connecting units 58, 60 to the position error synchros.

Connected in the mechanical linkage 65 (as shown in FIGS. 2 and 13A) between the position error synchros 62, 64, 66 and the table motor TM is a clutch EC3. This clutch is selectively disconnectable to allow move-

ment of the table without rotation of the position error synchros. The clutch is disengaged by closing the switch SW16. This allows errors between actual commanded position and desired commanded position to be corrected during machine setup for automatic operation.

Another table control unit is included in the machine. A table handwheel 88 (FIGS. 2, 3, 13C) is provided for complete manual control of the table motor TM. The table handwheel is connected through gear train 89 to the rotor windings of synchro transmitter 90 (FIGS. 3, 2) connected in series between the table synchro transmitter 36 and the table synchro receiver 30. Rotation of the handwheel 88 produces rotation of the handwheel synchro transmitter 90 and produces an error signal at the synchro receiver 30. The table motor TM is then energized and the table moves. The handwheel is always connected in the circuit and may be used to override the table control motor's effect on the table motor at any time.

The Wheelhead Mechanism

The grinding machine has a wheelhead 19 (FIGS. 1, 4) slidably received on cross ways 20 in the machine base 92. Fixed to the wheelhead and parallel to the ways is a rack 94. The rack is engaged by a pinion 96 which is driven both by a rapid traverse motor 98 and a wheelhead feed motor WM. The rapid traverse motor 98 provides a fixed amount of movement of the wheelhead 19 toward and away from the table 12. It is a motor of the rotating paddle type which has a housing 100 (FIG. 5) and a paddle portion 102 received in the housing. In this machine, the housing is rotatably received on a drive shaft 104 (FIG. 4) extending from the pinion 96. The drive shaft has the paddle portion 102 (FIG. 5) fixed thereto and received in the housing 100 of the rapid traverse motor 98. The housing has a radial wall 106 and the paddle 102 is made to swing from one side of the wall, 106, ground the housing cavity, and against the other side. When the paddle portion swings, the housing 100 is held stationary. Consequently, the drive shaft 104 turns and effects movement of the wheelhead by rotating the pinion 96 (FIG. 4) when the paddle is swung in the housing. The housing is held stationary by the inaction of the feed motor WM which drives a shaft 228 carrying a worm 108 engaged with a worm wheel portion 110 of the rapid traverse motor housing 100 during feed movement. The wheelhead motor WM is not operating when the wheelhead is moved in rapid traverse. The rapid traverse motor 98 is included in the feed drive train 118 between the feed motor WM and the wheelhead 19 and operates as a lost motion mechanism therein to produce the rapid movement of the wheelhead 19 without operation of the wheelhead motor WM.

The wheelhead motor WM is a rotary hydraulic motor in which the speed and direction of rotation are determined by operation of an electro-hydraulic servo valve 112 as shown in FIGS. 6 and 14C. The electrical error signals which operate the servo valve are produced at a wheelhead synchro receiver 114 of the resolver type. These error signals are taken from the synchro receiver 114 and amplified to a usable level in the wheelhead error amplifier 116 before they are connected to the servo valve 112. The rotor windings 114R of the wheelhead synchro receiver are mechanically connected by gear train 115 to the wheelhead motor WM for rotation when the wheelhead motor rotates. The servo valve 112 is connected to operate the wheelhead motor in a direction which tends to reduce the error signal at the wheelhead synchro receiver 114. Thus, when the wheelhead 19 has reached a position when the error signal produced at the synchro receiver is nulled, the wheelhead is stopped and remains stationary until an error signal is again produced at the synchro receiver.

An error signal is produced at the synchro receiver 114 when an electrical input signal is connected to the stator windings 114S thereof. This electrical input is induced when the rotor windings 120R, 166R, 138R of at least one

of the synchro transmitters 120, 166, 138, which are connected in series with the synchro receiver 114, and energized by source OSC connected to the stator windings of synchro transmitter 120, are rotated relative to the synchro receiver rotor windings 114R. The wheelhead motor circuit will see only one error signal, however, without regard to which transmitter, or transmitters cause the electrical signal to be induced in the receiver 114. Thus the rotation of the rotors, or armatures, of synchro transmitters 120, 166, 138, constitute mechanical command signals supplied to the signal generator (comprising the synchro transmitters 120, 166, 138 and the synchro receiver 114) which determine the control signal output from the signal generator defined by the error signal developed in the synchro receiver 114.

Rotary movement of the synchro transmitter 120 is produced in a control station 122 (FIG. 1) located at the front of the grinding machine to effect control of the wheelhead movement. The rotor windings 120R of the wheelhead feed synchro transmitter 120 are connected to the shaft 123 of wheelhead handwheel 124 for rotation therewith, as shown in FIG. 14C. When the handwheel 124 is manually rotated, an error signal is produced at the synchro receiver 114 which causes the wheelhead motor WM to be energized to move the wheelhead 19. Thus manual operation of the handwheel leads the wheelhead in manually directed movement. A wheelhead control motor WCM, stabilized by tachometer 125, is also included in the mechanism at control station 122 and may be selectively energized to rotate the handwheel 124. The wheelhead control motor WCM is energized by the electrical output of the wheelhead control motor amplifier 127. The wheelhead control motor is selectively connected to the handwheel for rotation thereof by a gear train 126 through operation of one of two clutches EC1 and EC2, as shown in FIG. 7A. Clutch EC2 has a forward gear 129 in mesh with forward gear 127' of clutch EC1 which is engaged with gear 131 on the shaft 123 of the handwheel. Clutches EC1 and EC2 have rear gears 133, 135 normally disconnected from the forward gears of the clutch, each engaged with gear 137 connected to the gear train 126. If electric clutch EC1 is energized the forward and rear gears thereof are connected and the control motor WCM is connected through gears 137, 133, 127, 131 to drive the handwheel 124 in a direction to produce movement of the wheelhead toward the worktable. If electric clutch EC2 is energized the forward and rear gears thereof are connected and the handwheel is connected to the control motor through gears 137, 135, 129, 127', 131 for rotation producing movement of the wheelhead away from the table. Since both directions of rotation of the handwheel are produced by the same rotation of the motor, except that one or the other of the two clutches is energized, when both clutches are energized, both the handwheel and control motor are locked against rotation. This locking is normally used in the machine when no wheelhead feed movement is desired.

Included in the wheelhead control station 122 is mechanism (FIG. 7A) which controls operation of the wheelhead control motor WCM through a preset cycle of operation to produce a predetermined grinding cycle. A handwheel positive stop 128 is included in the handwheel control mechanism. The handwheel 124 is adapted to engage the positive stop 128 when the positive stop is advanced and the handwheel is rotated to a reference position. Three rotatable cams 130, 132, 134 are provided in the mechanism. Each of the cams is mechanically connected for rotation by the wheelhead control motor WCM when the handwheel is rotated thereby and at a rate having a fixed relation to the rate of rotation of the handwheel. During feed out, or movement of the wheelhead away from the table, the cams 130, 132, 134 rotate clockwise (as viewed in FIG. 7B). During feed in, the cams rotate counterclockwise. The cams, which can be disen-

gaged from the handwheel, are angularly positionable relative to limit switch actuating arms 139a, 139b, 139c, 139d. The normal feed cam 130 is positioned during setup (with the handwheel against the positive stop) so that lobe 130a is spaced from limit switch actuating arm 139a an amount corresponding to the total amount of feed movement desired of the wheelhead in a grinding cycle as indicated by the angle 141. Cam 130, when geared in a one to one ratio with the handwheel, may be set to produce a total amount of feed corresponding to as much as one complete revolution of the handwheel 124 or any fractional part thereof. The fine feed cam 132 is positioned, in a similar manner, to preset an amount of fine feed movement into the grinding cycle. The fine feed cam closes a limit switch 2LS which must be held closed during the fine feed. Consequently, the angle 143 represents the total amount of fine feed available. The amount of fine feed is included in the total feed and is the part that takes place immediately before the handwheel engages the positive stop at the end of the infeed portion of a grinding cycle.

In machine operation through a grinding cycle, the table 12 (FIG. 1) is moved to position the diameter of the workpiece to be ground relative to the grinding wheel 18. The wheelhead is in the retracted position which gives clearance between the grinding wheel and the workpiece. The cycle is started. The wheelhead 19 (FIG. 4) is first fed away from the table 12 the preset amount determined by the normal feed cam 130 (FIGS. 7A, 7B) at a rate determined by the retraction feed potentiometer 12POT (FIG. 6) in the controller unit 136 electrically connected through amplifier 127 to the control motor WCM. When the wheelhead has moved the amount set by cam 130, the normal feed cam has moved clockwise (FIG. 7B) until it closes a limit switch 3LS and the rapid advance motor 98 (FIG. 4) is energized to move the wheelhead toward the work table a fixed amount, eliminating the clearance between wheel and workpiece. Since this rapid advance is effected independently of the wheelhead motor WM, the wheelhead control motor WCM is not operated during this rapid advance portion of the grinding cycle, so neither the handwheel 124 nor the cams 130, 132, 134 are rotated during rapid advance. At the end of the rapid advance, the wheelhead control motor WCM and clutch EC1 are energized. The wheelhead moves toward the table at a coarse feed rate. The coarse feed rate is set in a potentiometer 11POT (FIG. 6) which is included in the controller unit 136 electrically connected in the control motor circuit. After an amount of coarse feed, the fine feed cam 132 has moved back counterclockwise until it closes a limit switch 2LS which effects a change of rate control potentiometers in the controller 136 and the wheelhead control motor runs at a slower feed rate determined by the setting of a fine feed potentiometer 10POT. The fine feed continues until the handwheel engages the positive stop 128. When the positive stop is engaged, the control motor is stalled and infeed stops. A tarry timer is initiated by a limit switch 1LS which is operated when the handwheel is at the positive stop. At the end of the timed period, the control motor WCM is deenergized and the rapid traverse motor 98 (FIG. 4) is reversely operated. The wheelhead is rapidly withdrawn from the table an amount equal to the rapid advance and the grinding cycle is complete.

A third feed cam 134 (FIGS. 7A, 7B) is provided. It is an extended range cam, geared to rotate less than cam 130, and is effective to allow more than one revolution of the handwheel during feed. The cam 134 has two independently adjustable eccentric lobes which operate the pair of limit switches, limit switch 4LS having a pair of normally open contacts in series with normally open contacts of limit switch 3LS in the control circuit, and limit switch 5LS. Limit switch 4LS must be operated in order for limit switch 3LS to be effective to terminate the operation of the control motor at the end of feed out. Limit switch 4LS is operated by lobe 134a through arm 139c.

The number of revolutions of the handwheel during feed out is determined by the initial position of the extended range cam. One complete revolution of the extended range cam represents a fixed number of revolutions of the normal feed cam and of the wheelhead handwheel. When switch 3LS is operated after limit switch 4LS is operated, the feed out stops. Rapid wheelhead advance takes place, and feed in begins after that. The positive stop 128 is retractable by operation of solenoid 3SOL and advanced by operation of solenoid 2SOL. When limit switch 5LS is not operated, the positive stop is held retracted and the handwheel can make more than one complete revolution during infeed. The number of revolutions during infeed is determined by the adjustment of the extended range cam 134 and corresponds to the number of revolutions during feed out. During the last revolution of the handwheel 124 before the preset amount of feed is complete, the lobe 134b of the extended range cam operates limit switch 5LS through arm 139d to operate solenoid 2SOL and to extend the positive stop. Limit switch 5LS also renders the limit switch 2LS ineffective to initiate fine feed until limit switch 5LS is operated on the final revolution of the handwheel. Fine feed then takes place immediately before the positive stop is engaged. The extended range of feed is useful in moving the grinding wheel in along a shoulder on a workpiece to grind that shoulder as well as a diameter.

The wheelhead control motor WCM (FIG. 7A) is used in traverse grinding to generate a pickfeed movement of the wheelhead and the cycle control mechanism (FIG. 7A) is used to define the total amount of feed movement in a particular cycle. A pickfeed timer (2TR, FIG. 11A) is energized at selected times during the traverse cycle; for example, at each end of a table stroke. When the timer is energized and running, it effects energization of the wheelhead control motor WCM and the infeed clutch EC1 and deenergization of the retraction clutch EC2. The control motor runs at a rate fixed by a pickfeed potentiometer 13POT and for a time set by the pickfeed timer. This determines the amount that the wheelhead control motor rotates and consequently the amount that the handwheel 124 is rotated. After the timer times out, the control motor is deenergized and both clutches EC1, EC2 are energized, thus locking the handwheel against further rotation until one of the clutches is deenergized. The pickfeed continues in this way until the handwheel is moved against the positive stop 128. After this, the rapid traverse motor is reversed to retract the wheelhead.

The wheelhead control station 122 is an instrument simulation of the wheelhead 19 and wheelhead motor WM in which the control motor WCM corresponds to the wheelhead motor WM and the handwheel 124 corresponds to the wheelhead. The mass of the instrument setup is small and is easily controlled with great accuracy. The electrical signals produced as a result of the operation of the instrument setup which control operation of the wheelhead motor can be amplified with a high degree of fidelity and accuracy. The result is an accurate control of a mechanical system which has considerable mass.

The grinding machine is furnished with a mechanism to correctly and automatically position the wheelhead on the cross slide ways relative to the table and workpiece so that subsequent movement of the wheelhead through the preset grinding cycle will produce the desired diameter on the workpiece. While the wheelhead is being positioned, the wheelhead control motor is disabled by action of the control relay 68CR (FIGS. 6, 14C) which is deenergized during wheelhead positioning. At the same time that the wheelhead is being positioned prior to commencement of a grinding cycle, the worktable is positioned by the table control mechanism described to correctly position the workpiece diameter relative to the grinding wheel. The wheelhead positioning information is provided by the wheelhead position storage mechanism (61, 59, 162) from either the tape portion 61a and

reader 59 or a manually set dial system 198 (FIG. 14A) of the set of stepping switches 162.

The position synchro transmitter 138 (FIGS. 6, 14C) is connected in circuit with the wheelhead synchro receiver 114. When the rotor of the position synchro transmitter 138 is rotated, an error signal is produced at the synchro receiver 144 which energizes the wheelhead motor WM to move the wheelhead 19. Accurate control of the rotation of the position synchro transmitter 138 and close following of its movement by the wheelhead synchro receiver as driven by the wheelhead motor, gives a means of controlling the wheelhead to predetermined positions. Controlled rotation of the position synchro transmitter is effected by operation of a wheelhead position control motor WPCM. This motor is a two phase, 15 electric motor, stabilized by tachometer 140, which is operatively connected, as shown in FIGS. 6 and 14B, through gearing 142 to drive the rotor of the position synchro transmitter 138. Three position error synchros, a coarse resolver 144, a medium resolver 146, and a fine 20 resolver 148, similar to the table position error synchros 62, 64, 66 operate to produce an electrical output signal which operates motor WPCM. The magnitude of the output signal is used to effect proper switching by a two channel signal amplifier 150 containing a synchronizing network which effects connection of one only of the synchro elements into the control motor electronic circuit 152 at one time. The electronic circuit includes an amplifier 154, a phase detector 156, and a modulator 158 similar to electronic unit 70 in the table control mechanism. The output signal from the modulator 158 is then given proper drive in a position control motor amplifier 160 and passed to the control motor WPCM which is energized by the amplified output signal. The position control motor is mechanically connected through gear train 143 to rotate the position error synchro rotors in a direction tending to reduce the output signal from the effective position error synchro.

An output signal is produced at the position error synchros when the angular positions of the error synchro rotors do not correspond to the angular position defined by the sine and cosine components of the command signal introduced from the position stores mechanism. The wheelhead position command signals are produced from the set of stepping switches 162 which are set either manually by dials 198 or automatically from the same tape from which the table position command signals are produced. Like the table position command signals, the wheelhead position command signals include operating position command signals used to position the wheelhead for a grinding operation, and truing position command signals used to position the wheelhead for a truing operation. When an output signal is produced, the position control motor WPCM is energized to rotate the position error synchro rotors to angular positions corresponding to the command signal where the output signal is nulled. The wheelhead motor WM is energized when the position control motor is energized and follows operation of the position control motor. When the position error synchros are rotated to the null position corresponding to a predetermined position command signal, the wheelhead motor is stopped and the wheelhead is in a position corresponding to the position command signal. With both the wheelhead and table positioned, the grinding cycle is started.

In order that the command signal define a predetermined position of the wheelhead, the wheelhead must have a reference position to which the command signals are related. This reference position is initially defined by truing the grinding wheel 18 (FIG. 4) such that its cutting surface is in a known position relative to a fixed reference point. In setup preparatory to automatic control, a value corresponding to a reference diameter is set by the dials 198 which determine the operation of the stepping switches in unit 162 of the position storage mech-

anism to produce a predetermined command signal corresponding to the value of the reference diameter. The wheelhead moves to a position corresponding to the dials setting and the output signal from the position error synchros nulls. The rapid traverse motor is then energized to advance the wheelhead through its fixed stroke toward the work table. The wheelhead position is adjusted manually by rotation of rotor windings 120R with handwheel 124 to bring the grinding wheel 18 into dressing contact with the truing tool 22 while the wheelhead 19 is in the advanced position. The handwheel 124 (FIG. 7A) is disengaged from shaft 123 by pulling out knob 124a to disengage gear 123a, which is keyed to shaft 123, from gear 124b, which is fixed in the handwheel, and the handwheel is rotated to engage the positive stop 123. The truing tool 22 which is mounted on the tailstock on the table has a diamond point 164 located a fixed distance from the axis of the workpiece. This fixed distance is equal to the radius of the reference diameter. After the wheel is trued, the wheelhead is retracted by operation of the rapid traverse motor. The wheelhead is then in the initial reference position. All succeeding position command signals introduced into the position error synchros are related to the truing command signal. The wheelhead will be automatically brought to a position related to a reference position as the position command signal is related to the truing command signal established during wheel truing. Each time the wheel is trued, the truing command signal is introduced to position the wheelhead.

In order to true the wheel after a grinding operation, without changing the truing command signal, an independent adjustment of the wheelhead reference position must be made during the dressing operation to compensate for grinding wheel attrition. This adjustment is made by compensation unit 165 which effects rotation of the rotor windings 166R of a compensation synchro transmitter 166 (FIGS. 6, 14C, 8, 9) of the resolver type. The compensation synchro 166 is connected in circuit with the wheelhead synchro receiver 114 and is operative to produce an error signal at the wheelhead synchro receiver when rotated. The compensation synchro transmitter 166 is mounted in the compensation unit on a gear segment 168, as shown in FIG. 8 and 9. Its rotor is rotatable relative thereto by operation of a compensation control stepping motor 6SS of the compensation unit. The stepping motor 6SS moves a ratchet pawl 172 which incrementally moves a ratchet wheel 174. Fixed to the ratchet wheel is a pinion gear 176 (FIG. 9). The pinion gear is engaged by a synchro gear 178 fixed to the rotor of the compensation synchro transmitter 166. When the stepping motor 6SS is energized and then de-energized, the ratchet wheel 174 moves a fixed increment of rotation. The ratchet wheel 174 rotates the synchro transmitter gear 178. This rotation of the synchro transmitter gear produces rotation of the rotor of the synchro transmitter 166 and an error signal at the synchro receiver 114 (FIG. 6) which causes the wheelhead to move in toward the worktable a fixed incremental amount. The movement of the wheelhead resulting from this truing compensation pickfeed does not alter the truing command signal produced by the wheelhead position stores 162 but does correct the reference position of the wheelhead 19 (FIG. 4) to account for the reduced diameter of the grinding wheel 18.

The compensation unit 165 performs another function. If a perfect gear train were available for driving the wheelhead by the wheelhead motor, the machine wheelhead movement would be accurate and linear, that is, bear a constant proportion to any rotation of the wheelhead motor WM (and hence to any command signal supplied to the motor servo valve) over its entire range. There are, however, inherent inaccuracies in gearing systems such as the rack and pinion drive of the wheelhead 19 which cause slight variation from linear movement, de-

pending upon where the wheelhead is in its path of movement. Therefore, the compensation unit includes a correction cam 180 (FIG. 10) fixed by pins 181 to the wheelhead 19. The cam has a surface which varies with the non-linearity of movement of the wheelhead produced by inaccuracies in the wheelhead drive mechanism. This cam is engaged by a cam follower 182 (FIGS. 8, 9, 10) biased toward the cam by a spring 183. The cam follower has a rack portion 184. The cam follower is slidably received in the compensation unit housing 186 by 10 antifriction rollers 188 and the rack portion 184 is engaged by the gear segment 168. The gear segment is pivotally mounted in the compensation unit housing 186 (FIG. 10) that is fixed on the machine base 92 by machine screws 93. When the cam follower is moved toward and away from the cam surface, the gear segment 168 (FIGS. 8, 9) is pivoted. The gear segment 168 carries the compensation synchro transmitter 166 which has the gear 178 fixed to its rotor and engaged with the pinion gear 176 fixed to the ratchet wheel 174. The pinion gear 176 is located on and rotates around the axis about which the gear segment 168 pivots. When the stepping motor 6SS is inactive, the ratchet wheel 174 is held fixed relative to the compensation unit housing 186. Thus when the segment 168 pivots, the synchro gear 178 is rolled on the pinion gear 176 to produce a slight rotation of the rotor of the synchro transmitter 166. This rotation creates an error signal component at the wheelhead synchro receiver during movement of the wheelhead which modifies any command signal and compensates for inaccuracies in the mechanical portions of the wheelhead drive between the wheelhead motor and the wheelhead.

Hydraulic Circuit

FIG. 15 shows the wheelhead and table hydraulic circuit for the grinding machine described. Fluid under pressure comes from the pump 200 through line 202 to the wheelhead start stop valve 204 which is operated by solenoid 4SOL. When that solenoid is energized, the plunger in the valve 204 moves to the right and connects pressure line 202 to line 206. Fluid under pressure then passes through the throttle valve 208 through line 210 to the paddle motor 98, the wheelhead rapid traverse motor, and forces the paddle segment 102 to swing counter-clockwise relative to the motor housing. The motor housing is held in a fixed position by the worm 108 engaged with the worm wheel portion 110 of the housing. The worm is carried by shaft 228 which is driven by the wheelhead motor WM and is inactive during rapid movement of the wheelhead. The paddle segment is fixed to the shaft 104 which has pinion gear 96 fixed on one end. The pinion gear is engaged with rack 94 which is fixed to the wheelhead 19. Therefore, as the paddle segment swings, the pinion 96 is rotated to drive the wheelhead forward, the amount of movement determined by the amount of swing allowed in the paddle motor. Exhaust fluid, forced out ahead of the paddle segment as it swings, passes through line 212, ball check 214, and line 216 to the start stop valve 204 where it connects to the main return 218.

Reduced pressure is connected through line 220 to the right side of the cylinder 222. The reduced pressure is provided by the reducing valve 224. As the wheelhead 19 moves, the cylinder 222 moves. The piston 226 is fixed to the machine base 92. The pressure in the cylinder is maintained at a constant value by the valve 224 and produces a force between the wheelhead and the base which maintains the backlash between gears in the driving gear train 118 in a fixed state regardless of wheelhead direction of movement.

When the wheelhead has completed its rapid movement toward the table, pressure switch PS1 closes limit switch 112 and starts the infed movement. The electro-mechanical transducer portion 227 of the servo valve 112 is mechanically connected to the plunger of the servo

valve 112 and electrically connected to the output of the wheelhead error amplifier 116 (FIG. 6). The valve 112 controls operation of the wheelhead motor WM in accordance with the electrical output of the wheelhead error amplifier. The wheelhead motor drives the shaft 228 which drives worm 108 connected to the worm wheel portion 110 of the paddle motor. As the wheelhead motor is energized, the paddle motor and shaft 104 rotate together to move the wheelhead. Pressure is connected to the valve 112 by line 202. If the plunger of the servo valve 112 is to the right, line 230 is connected to pressure and line 232 is connected to return line 218. The wheelhead motor drives in one direction. If the plunger position is reversed, the valve reverses the pressure and return connections and the wheelhead motor drives in the other direction. The rate at which the wheelhead motor is driving is determined by the amount of movement of the plunger of the valve 112 from the center or neutral position. This is controlled by the magnitude of the signal from the wheelhead error amplifier.

At the end of the feed movement toward the table, and after a tarry period or a number of dead passes, solenoid 4SOL is deenergized and the plunger of valve 204 is shifted back to the left as shown. Line 206 is connected to the return line 218 and line 216 is connected to pressure line 202. Fluid under pressure passes through the throttle valve 234 to line 212 and into the paddle motor to swing the paddle segment clockwise to effect rapid retraction of the wheelhead. When the wheelhead has retracted and the paddle has completed its swing, pressure switch PS2 closes the limit switch 111LS.

The table 12 is driven by the table motor TM which is controlled by operation of the servo valve 28 which includes valve portions 28a, 234, and 236 and transducer portion 238. The plunger of valve portion 28a is positioned by operation of the pilot valves portions 234 and 236 whose plungers are connected to the torque motor 238, the electro-mechanical transducer in the table drive mechanism. When the torque motor swings clockwise, the reduced pressure from valve 240 in line 242 is connected to line 244. Line 244 connects to the right side of the plunger in valve portion 28a. Line 248 is connected directly to the reservoir or ground through valve portion 234 and there is no pressure on the left end of the plunger in valve portion 28. The plunger in valve portion 28 then is shifted left due to a pressure differential between its ends. Pressure from line 202 is then connected to line 249 which connects to the table motor. Line 246 from the table motor is connected to return line 218. If the torque motor 238 swings counter-clockwise, the line 248 is connected to pressure through valve portion 234 and line 244 is connected to return through valve portion 236. The plunger in valve portion 28 shifts to the right and line 246 is connected to pressure line 202 while line 249 is connected to return line 218 to reverse the operation of table motor TM. The lever 250 pivotally connected to the plunger of valve portion 28a is a mechanical feedback linkage to the pilot valve portions 234 and 236 to insure that the amount of movement of the plunger of valve portion 28a is in accordance with the electrical signal from the table error amplifier. The magnitude of the signal from the table error amplifier determines the amount that the torque motor will swing, and hence the amount of movement of the plunger of portion 28a from a center position which movement determines the rate at which the table motor runs.

Electrical Operation, Automatic Cycle

70 Portions of the electrical circuit of the machine are shown in FIGS. 11A through 11H and FIGS. 12A through 12C in which horizontal reference locations will be given as a number suffixed by a single L and parenthesized. Switch SW15 (4L) is momentarily closed to 75 energize relay 109CR which is latched by its own con-

tacts. When switch SW14 is opened, relay 100CR is de-energized. When the contacts of relay 100CR (6L) are closed a voltage appears across conductors 1LL and 2LL. Conductor 1LL is at ground potential. Conductor 2LL is a supply voltage line at 110 volts. Connected across the lines 1LL and 2LL is a power supply 190 which furnishes +250 v. D.C., -150 v. D.C., and 6.3 v. A.C. currents to the various electrical and electronic units of the machine. A 400 cycle oscillator OSC supplies 400 cycle reference voltage to some of the resolvers used in the machine control mechanism, the sets of stepping switches (58, 60, 162), and some of the amplifiers. A 48 volt direct current power supply 191 furnishes the control relay voltage, there being 48 volts control voltage on line 3LL when switch SW15 is closed.

In considering the electrical control circuit of this machine, it is convenient to break the description into parts, each part describing a particular mode of operation of the machine. The first mode of operation to be considered is plunge grinding through an automatic cycle with manual control of the starting position from which the wheelhead moves when the cycle is initiated. Selector switch SW1 (FIG. 11B, 67L) is placed in the hand position and selector switch SW2 (52L) is placed in the plunge position. Control relays 16CR (67L) and 13CR (52L) are energized to pick up. When relay 16CR is picked up, relays 17CR (FIG. 11C, 68L), 17ACR (69L), and 17BCR (71L) are picked up through the contacts of relay 16CR (70L). Relay 71CR (FIG. 12B, 231L) is then picked up through contacts of relays 14CR, 15CR, and 17ACR to disable the table control motor TCM (FIG. 13C) by grounding the output of amplifier 44 through resistance 44R. When relay 13CR is up, relay 11CR (56L) is also picked up through contacts of relay 13CR and normally closed contacts of relay 39ACR. (Relay contacts are shown in their deenergized positions. The contacts of relay 13CR at reference location 56L are shown as normally open, while the contacts of relay 39ACR at reference location 56L are shown as normally closed.) When relay 11CR is energized, its normally closed contacts in the wheelhead control motor clutch circuit (FIG. 14C) are opened, and the electric clutches EC1 and EC2 are deenergized. When both clutches are deenergized, the wheelhead handwheel 124 (FIG. 14C) may be used to manually position the wheelhead. The wheelhead advance switch SW3 (FIG. 11B, 60L) is also active and may be used to rapidly advance the wheelhead toward the worktable when closed. Relays 30CR and 30ACR (FIG. 11E, 134L, 136L) are picked up through normally closed contacts of 39ACR and conductor 5LL when the switch SW3 is closed to energize 4SOL and operate the rapid traverse motor. If the wheelhead has been advanced during setup, switch SW4 (FIG. 11B, 60L) may be momentarily opened to deenergize relays 30CR and 30ACR (and hence solenoid 4SOL) to retract the wheelhead before automatic operation is begun. Before the hand-automatic plunge cycle, the workpiece diameter to be ground is positioned relative to the grinding wheel by manual table movement. The wheelhead is moved to its proper place on the cross slide ways and the handwheel 124 adjusted to engage the positive stop. The grinding cycle control cams 130, 132, 134 are adjusted for the proper stock removal. The machine is now set for initiation of the automatic plunge grinding cycle by the operator.

The cycle start switch SW5 (58L) is closed to initiate the cycle. Control relay 39CR (FIG. 11F, 152L) is picked up directly through a section of switch SW5 (151L) and 39ACR (153L) is picked up through contacts of relay 16CR, the switch SW5 (58L), and conductor 8LL. Relay 39CR latches through contacts of relays 21CR and 39CR and a section of the cycle stop switch SW6 (152L). Relay 39ACR latches through contacts of relays 65CR and 39ACR, the normally closed, time open,

instant close contacts of tarry timer 1TR, and a section of the cycle stop switch SW6. When relay 39ACR is energized, relay 11CR (FIG. 11B, 56L) is dropped. The electric clutches EC1 and EC2 (FIG. 14C) are both energized, EC1 through normally closed contacts of relay 40CR, and EC2 through normally closed contacts of relays 43CR, 37CR, and 63CR. The handwheel 124 is still engaged with the positive stop 128 and the contacts of limit switch 3LS (150L) are not closed. Relay 38CR (150L) will not pick up. The wheelhead is in the retracted position with limit switch 111LS operated and the contacts thereof (FIG. 11E, 142L) closed. Relay 33CR (142L) is picked up through the contacts of limit switch 111LS. With the circuit in this condition, relays 40CR (FIG. 11F, 155L) and 40ACR (156L) are picked up through contacts of relays 33CR, 39ACR, 38CR and 52CR. When relay 40CR is energized, relay 68CR (FIG. 11H, 217L) is caused to pick up. When relay 68CR is energized the wheelhead control motor is energized to run since the normally open contacts of relay 68CR in the circuit of control motor WCM are closed (FIG. 14C) to apply energizing voltage thereto.

Now that relay 40CR is energized and its normally closed contacts in the clutch circuit (FIG. 14C) are opened clutch EC1 is deenergized while clutch EC2 is energized. Clutch EC2 is the feed out clutch and the wheelhead control motor drives the handwheel away from the positive stop. The rate at which the control motor runs is set by the feed out potentiometer 12POT (FIG. 14B) which is tied into the control motor amplifier 127 and conductor 4LLL by contacts of relay 40CR. After the wheelhead has fed out a preset amount of total feed, the contacts of limit switch 3LS (150L) are closed when limit switch 3LS is operated by the total feed cam 130 (FIGS. 7A, 7B). (The extended range cam 134 is assumed to be set so that no extended range is provided for and limit switch 4LS (FIG. 7A) is operated and its contacts at 1SOL are closed.) When limit switch 3LS is operated, relay 38CR (FIG. 11F, 150L) is picked up. Relays 40ACR and 40CR are then dropped and the feed out is stopped as relay 68CR is dropped and the control motor is disabled. Both clutches EC1 and EC2 are energized to lock the handwheel when relay 40CR is dropped.

When relay 38CR is picked up, relays 39CR (FIG. 11E, 134L) and 30ACR (136L) are picked up through contacts of relays 39ACR and 38CR and latch through contacts of relays 11CR, 30CR, 65CR, contacts of switch SW6, and the normally closed, time open, instant close contacts of tarry timer 1TR. Solenoid 4SOL (FIG. 11A, 3L) is energized by relay 30ACR and the rapid traverse motor is energized to move the wheelhead rapidly toward the workpiece. This releases pressure switch PS2 and releases limit switch 111LS to drop relay 33CR (FIG. 11E, 142L). At the end of the rapid advance stroke, contacts of limit switch 112LS (FIG. 11E, 143L) are closed and relay 34CR (143L) is energized. When relay 34CR is energized, relay 43CR (FIG. 11F, 159L) is picked up through contacts of relays 38CR, 34CR, 67CR, 58CR, and 37CR. Relay 44CR (161L) is also picked up through contacts of relays 38CR, 34CR, and 67CR. When relay 43CR is energized, relay 68CR (FIG. 11H, 217L) is again up to energize the wheelhead control motor WCM (FIG. 14C). The control motor runs at a rate set by the coarse feed potentiometer 11POT (FIG. 14B) which is now tied into the control motor amplifier by contacts of relay 43CR. Relay 43CR being up, opens its normally closed contacts in the clutch circuit (FIG. 14C) and clutch EC2 is deenergized. The control motor now drives the handwheel toward the positive stop, at the coarse feed rate. As the handwheel begins to move toward the positive stop cam 130 releases limit switch 3LS and the contacts of limit switch 3LS (FIG. 11F, 150L) are opened and relay 38CR is dropped. As the handwheel is rotated, resolver rotor windings 120R 75 are rotated and the wheelhead motor is energized to

move the wheelhead toward the workpiece and the worktable.

At a preset point before the handwheel engages the positive stop, the fine feed cam 132 (FIGS. 7A, 7B) operates limit switch 2LS and its contacts at 148L (FIG. 11F) are closed. (Since there is no extended range set in, limit switch 5LS is also closed and relay 45CR at 162L, is picked up.) Relay 36CR (148L) picks up through contacts of relay 45CR, limit switch 2LS, conductor 7LL, and contacts of relay 44CR (FIG. 11E, 145L). Relay 37CR (149L) then picks up through contacts of relays 44CR, 58CR, 36CR and 40CR and conductor 7LL. Relay 43CR (159L) is dropped as relay 37CR comes up and the fine feed potentiometer 10POT (FIG. 14B) replaces the coarse feed potentiometer in the controller circuit of the control motor amplifier. Relay 37CR also holds relay 68CR (FIG. 11H, 217L) energized to continue operation of the wheelhead control motor at the reduced rate of speed.

At the end of the fine feed, the positive stop 128 (FIG. 7A) is engaged by the handwheel 124 and the control motor is stalled. Limit switch 1LS (FIG. 11E, 144L) is closed and relay 35CR (144L) is picked up through contacts of relays 44CR, 67CR and switch 1LS. The tarry timer 1TR (FIG. 11A, 19L) is energized through contacts of relay 35CR, 52CR, and 57CR when relay 35CR is energized. After a preset period of time during which the wheelhead is stopped with the grinding wheel against the workpiece the timer times out and is deenergized. When timer 1TR is deenergized, the contacts (153L) thereof momentarily open to remove the latch from relays 39ACR (FIG. 11F, 153L) 30CR (FIG. 11E, 134L), and 30ACR (136L). These relays are deenergized. When relay 39ACR is deenergized, relay 11CR (FIG. 11B, 56L) is energized and both clutches EC1 and EC2 are now deenergized. Solenoid 4SOL (FIG. 11A, 3L) is deenergized when relay 30ACR is deenergized and the rapid traverse motor is reversely operated to retract the wheelhead from the workpiece. Relay 34CR is deenergized as pressure switch PS1 is released and the contacts of limit switch 112LS (FIG. 11E, 143L) are opened. When relay 34CR is deenergized relay 44CR (FIG. 11F, 161L) is deenergized. Relays 35CR (FIG. 11E, 144L), 36CR (FIG. 11F, 148L), and 37CR (FIG. 11F, 149L) are all dropped when the contacts of relay 44CR (FIG. 11E, 145L) are opened. Relay 68CR (FIG. 11H, 217L) is deenergized when relay 37CR is dropped. Pressure switch PS2 is operated to close the contacts of limit switch 111LS (FIG. 11E, 142L) and relay 33CR is picked up. The control circuit is now in condition once again and ready for another cycle to be initiated by closing the switch SW5 (FIG. 11B, 58L).

For a coarse traverse grinding operation, the selector switch SW2 (55L) is placed in the center position. Relays 11CR (56L) and 13CR (52L) are not energized. Selector switch SW1 (67L) is retained in the hand position. Relays 16CR (FIG. 11B, 67L), 17CR (68L), 17ACR (69L), and 17BCR (71L) are picked up. The work table 12 is moved manually between reversing points by operation of the table handwheel 88 to set the table dogs 54 for engagement of reversing lever 50 (FIG. 3) at the reversing points. The table is stopped at a position between reversal points and the cycle is ready for initiation. The cycle start switch SW5 is closed and the cycle is begun. The wheelhead movement and operation of the control mechanism proceeds as in the plunge grind operation described until the end of the rapid advance stroke when limit switch 112LS is operated to close its contacts (FIG. 11E, 143L) and relay 34CR (143L) is picked up. Since relay 13CR is deenergized and relay 17BCR energized, relay 67CR (FIG. 11G, 190L) is picked up through contacts of relays 13CR, 17BCR and 58CR. Limit switches 106LS and 107LS (FIG. 3) are both operated by the detented table reversing lever 50 and one or the other is always operated. Assume that

switch 106LS is operated initially and its contacts closed. Relay 14CR (62L) is then caused to pick up through contacts of relays 17CR, 67CR, 34CR and 39ACR, and limit switch 106LS. Relays 14CR and 15CR (63L) control the traverse switcher circuit 52 (FIG. 13B). By reversing the connection of the primary winding of transformer 33 across the 110 volt source, this circuit controls the direction of drive of the table control motor TCM (FIG. 13C). When relay 14CR is picked up, the relay 71CR (FIG. 12B, 231L) is deenergized and the rapid traverse switcher 52 (FIG. 13B) is electrically connected through the conductor 2LL and the table control motor amplifier 44 (FIG. 13C) to the table control motor TCM through normally closed contacts of the relay 71CR. Prior to its deenergization, relay 71CR was energized through normally closed contacts of relays 14CR and 15CR and contacts of relay 17ACR (FIG. 12B, 229L, 230L) to disable the table control motor TCM by grounding the output of the table control motor amplifier 44 through the resistor 44R. With relay 71CR deenergized and relay 14CR energized, the table begins to feed to the left at a rate controlled by the setting of the potentiometer 46 in the table traverse switcher 52 (FIG. 13B). When relay 14CR became energized relay 108CR (45L) became energized through contacts of relays 64CR, 30CR and 14CR. When the table arrives at the left end of its stroke the reversing lever 50 is hit by a dog 54 on the table 12 and limit switch 106LS is released, opening the contacts thereof (FIG. 11B, 62L). Relay 14CR is dropped, limit switch 107LS is operated and the contacts (63L) thereof are closed, and relay 15CR is picked up. When relay 15CR is picked up, relay 109CR (51L) is picked up. The relay 108CR (45L), which is latched through contacts of its own, and relay 109CR (51L), also latched through contacts of its own, are both energized at the same time. When this occurs, relay 59CR (FIG. 11H, 208L), a delayed release relay, picks up through contacts of relays 17ACR, 108CR, and 109CR. Relay 64CR (203L) now picks up through contacts of relays 30CR (FIG. 11E, 144L), 59CR, 27CR, and normally closed contacts of 64CR. Relay 64CR latches through contacts of relays 64CR and 48CR, and timer 3TR. When relay 64CR is picked up, the relay 71CR (FIG. 12B, 231L) is picked up through contacts of relays 64CR, 19CR, and conductor 17LL (FIG. 11G, 198L) to disable the table control motor TCM by grounding the output of the table control motor amplifier 44 (FIG. 13C) through resistor 44R. Relays 64ACR (206L) and 63CR (207L) also are energized when relay 64CR is picked up. The pick feed distance timer 2TR (FIG. 11A, 24L) is set off when the contacts of relay 64ACR (25L) are closed.

The position of selector switch SW8 (FIG. 11A, 25L) determines where in the table stroke that pickfeed takes place. If the selector switch SW8 is in the center position, the wheelhead will pickfeed at each end of the table stroke. The voltage developed across potentiometer 7POT when the contacts of relay 64ACR (25L) are closed determines the length of the timed period. Potentiometer 7POT is connected in the timer circuit at each end of the table stroke when selector switch SW8 is in the center position since there is no complete shunt circuit around potentiometer 7POT. If selector switch SW8 is in the left position, a shunt path therethrough exists when the table is at the right end of its stroke and the contacts of relay 14CR (27L) are closed. Therefore no voltage is developed across the potentiometer 7POT and there is no timed period and the contacts 2TR (FIG. 11H, 207L) are not opened. If the selector switch SW8 is in the right position, a shunt path around potentiometer 7POT exists when the table is at the left end of its stroke and the contacts of relay 15CR (27L) are closed. In such a case, the timer would not be operated.

Assuming switch SW8 is set in the center position, when the contacts of relay 64ACR (25L) close when the table

12 is at the left end of its stroke, the contacts of timer 2TR (29L) are closed and the table tarry timer 3TR (28L) is set off. When the table is at the left end of its stroke and relay contacts 15CR (31L) are closed, the voltage across potentiometer 9POT determines the length of the table tarry. (When the table is at the right end of its stroke and relay contacts 14CR (29L) are closed, the voltage developed across potentiometer 8POT determines the length of the table tarry period.) Both relays 108CR and 109CR are deenergized when relay 64CR is energized. At the end of 40 microseconds after relays 108CR and 109CR are dropped, relay 59CR, which is energized through contacts of these relays (FIG. 11H, 208L), is dropped, but relays 64CR, 64ACR and 63CR are latched through the normally closed, time open, instant close contacts of table tarry timer 3TR (203L). When relay 63CR picks up, relay 68CR (217L) picks up to start the wheelhead control motor WCM (FIG. 14C) which runs at a rate determined by the pickfeed potentiometer 13POT (FIG. 14B). The pickfeed potentiometer is placed into the wheelhead control motor circuit by operation of relay 63CR. Clutch EC2 (FIG. 14C) is deenergized when relay 63CR picks up so that the handwheel 124 (FIG. 14C) is rotated through the infeed clutch EC1. The wheelhead is led toward the workpiece by the wheelhead control motor WCM. At the end of the pickfeed timer period, the normally closed, time open, instant close contacts of timer 2TR at relay 63CR (FIG. 11H, 207L) are opened to drop that relay and both clutches EC1 and EC2 are again energized. When relay 63CR is dropped, relay 68CR (217L) is dropped and the wheelhead control motor WCM is disabled. The wheelhead has been advanced toward the workpiece an amount determined by the rate of operation of the wheelhead control motor (as established by the setting of potentiometer 13POT) and the length of time which the control motor runs determined by setting of the potentiometer 7POT (FIG. 11A, 26L) in the pickfeed timer 2TR. The table tarry timer 3TR now times out and relays 64CR (FIG. 11H, 203L) and 64ACR (206L) are dropped. As relay 64CR drops, relay 109CR (51L) is energized through contacts of relays 64CR, 30CR, and 15CR, and the disable relay 71CR (FIG. 12B, 231L) is dropped. The table begins to move to the right since relay 15CR (63L) has changed the traverse switcher 52 (FIG. 13B) to cause control motor TCM to lead the table motor TM to drive the table in that direction.

The table moves to the right until limit switch 106LS is operated to close its contacts (FIG. 11B, 62L) and again pick up relay 14CR. The contacts of limit switch 107LS (63L) are opened, to drop relay 15CR. Relay 108CR (45L) is again energized while relay 109CR is energized and relay 59CR (FIG. 11H, 208L) is picked up again. Relay 64CR (203L) is also picked up again. The pickfeed timer 2TR is started if selector switch SW8 is set for operation at the right, and the table tarry timer 3TR is again started. The wheelhead is caused to pickfeed as described for the left end of the table stroke while the table tarries at the right end of its stroke.

The pickfeed and table traverse continue until the wheelhead handwheel 124 has moved against the positive stop 128. Further pickfeed is then prevented, but the traverse movement of the table continues through operation of the dead pass stepping switch 7SS bank B and selector switch SW9 (FIG. 11H, 213L). As the handwheel engages the positive stop, contacts of the limit switch 1LS (FIG. 11E, 144L) close and relay 35CR (144L) picks up through contacts of relays 30CR and 67CR and limit switch 1LS. Before the relay 35CR is picked up the stepping motor of stepping switch 7SS (FIG. 11H, 210L) is energized through the normally closed contacts of relay 35CR (212L), and the home open contacts 7SS HOME and the interrupter break contacts 7SS INT of the stepping switch 7SS if that switch is not already in its home position. Upon en-

ergization of the motor of stepping switch 7SS, the interrupter break contacts 7SS INT open and the switch motor is deenergized. The energizing and deenergizing results in one step of the stepping switch. At the end of the 5 step, the interrupter contacts 7SS INT are again closed. The motor is again energized to begin to move and the interrupter contacts 7SS INT again open. Movement of the stepping switch is abruptly stopped and another step is made. This stepping movement continues until the stepping switch 7SS is in the home position and its 10 home opened contacts 7SS HOME are open to prevent further energizing of the motor thereof until the relay 35CR is picked up. Relay 57CR (FIG. 11G, 193L) has been picked up from the start of the traverse grind operation through the contacts of relay 67CR. After the handwheel engages the positive stop, and stepping switch 7SS is in the home position, stepping switch motor 7SS (FIG. 11H, 210L) is energized through relay contacts of 35CR, 55CR, 57CR, 16CR, 59CR, and 64ACR. Now 15 when relay 64ACR is picked up and during the time that the table is at a reversing point, the stepping motor 7SS is deenergized. When the stepping motor is deenergized, the wiper contact 7W (FIG. 11H, 212L) is advanced to the right to the next contact of stepping switch 20 7SS bank B. When the table begins to move after the tarry time period, relay 64ACR is dropped and the stepping motor 7SS is energized. Each time the table reaches a reversing point, the relay 64ACR is picked up and the wiper 7W of the stepping switch is advanced one 25 contact further around stepping switch 7SS bank B. The setting of the dead pass selector SW9 (213L) determines the number of passes to be made after the handwheel engages the positive stop and before the wheelhead is retracted. When the wiper contact 7W has moved to the 30 position set by selector switch SW9 during the time that relay 64ACR is energized, relay 65CR (213L) is energized. Relays 39ACR (FIG. 11F, 153L), 30CR (FIG. 11E, 134L), and 30ACR (136L) are dropped. Solenoid 4SOL (FIG. 11A, 3L) is deenergized and the wheelhead moves rapidly back from the workpiece and stops at the end of the rapid retraction stroke. Relay 33CR is energized as the contacts of limit switch 111LS (FIG. 11E, 142L) are closed. Relay 34CR is dropped when the wheelhead is retracted and whichever of relays 45 14CR (FIG. 11B, 62L) or 15CR (63L) that was energized at the end of the final table stroke is deenergized. When relay 30CR is dropped to effect rapid retraction, relays 108CR (45L) and 109CR (51L) are prevented from picking up and relay 64CR (FIG. 11H, 203L), 50 64ACR (206L), and 63CR (207L) are dropped before the end of the timer period. Relay 65CR (213L) as also dropped when relay 64ACR is dropped.

If the selector switch SW2 (53L) is placed in the lower, or fine traverse, grind position while the switch SW1 (FIG. 11B, 67L) is in the hand position, relay 55 58CR (FIG. 11G, 191L) will be picked up through conductor 11LL (FIG. 11B, 53L), relay 17CR, and contacts of the switch SW2. If the cycle start switch SW5 (58L) is closed the wheelhead is first fed out, then rapidly moved in, and finally fed through the coarse plunge 60 movement of the hand automatic plunge grind cycle described until contacts of limit switch 2LS (FIG. 11F, 148L) are closed by the fine feed cam 132 (FIGS. 7A and 7B) which will be set to operate limit switch 2LS before the grinding wheel contacts the workpiece. Relay 65 36CR (148L) is then energized as described but relay 37CR (149L) is not energized. Either relay 14CR (FIG. 11B, 62L) or relay 15CR (63L) is picked up through contacts of relays 17CR, 58CR, 36CR, 34CR, and 39ACR. The table begins to move and the wheelhead is fed in toward the table in increments as in the coarse traverse grinding operation until the handwheel reaches the positive stop. The preset dead passes will be made and the wheelhead rapidly retracted at the end 70 75 of the cycle, also in the same manner as the coarse

traverse grind operation, to complete the fine traverse grind operation.

Electrical Operation, Dial's Control for Positioning Wheelhead

Three automatic grinding cycles have been described thus far: plunge, coarse traverse, and fine traverse cycles. In addition, the capability for manual movement of the wheelhead and table has been pointed out so a complete manual cycle can be executed or so these machine units can be manually positioned for the automatic grinding cycles described. The machine is also operable to effect automatic positioning of the wheelhead before an automatic grind cycle is commenced. Selector switch SW1 (FIG. 11C, 69L) is placed in the dials position and the switch SW2 (FIG. 11B, 52L) is in, for example, the plunge position. With the switches SW1 and SW2 in the dials and plunge positions respectively, relays 11CR (FIG. 11B, 56L), 13CR (52L), 17CR (FIG. 11C, 68L), 17ACR (69L), and 17BCR (71L) are all picked up. The dials comprising the dials system 198 (FIG. 14A) are hand set for the diameter of workpiece to be ground. These dials determine the position to which the wiper contacts of the individual stepping switches Y1SS, Y2SS, Y3SS, Y4SS, Y5SS, Y6SS (FIG. 12C, 238L through 243L) of the set of stepping switches 162 (FIG. 14A) in the wheelhead position storage mechanism will be moved. For each of these stepping switches there is shown the wiper contacts W7 and W8 of each switch which are operated by the stepping switch motor and are automatically positioned in accordance with the settings of the dial wiper contacts 198A, 198B, 198C, 198D, 198E, and 198F, respectively, which are mechanically connected to the dials 198 for positioning. Each switch has a bank of contacts (Y1A, Y2A, Y3A, Y4A, Y5A, Y6A) over which the wiper W8 sweeps, a bank of contacts (Y1B, Y2B, Y3B, Y4B, Y5B, Y6B) over which the wiper W7, which moves in unison with wiper W8, sweeps. Each switch also has a pair of banks of contacts (not shown) over which a pair of wiper contacts (not shown) sweeps, which pair of wiper contacts moves in unison with wiper contacts W7 and W8 and hence is positioned in accordance with the settings of the dials 198.

Thus the digital information determined by the setting of dials 198 is automatically transformed into a predetermined setting of the Y axis stepping switches. The information storage mechanism includes a trigonometric store (not shown) energized from a reference voltage source and connected to the position error synchros through the pairs of wiper contacts (not shown) of the stepping switches to provide a command signal in accordance with the setting of dials 198. Each pair of wiper contacts picks off a sine and cosine voltage component from the reference voltage, and the components picked off by the several pairs of stepping switch wiper contacts are combined to provide an accurate command signal comprising a sine and cosine component which, when supplied to the appropriate position error synchro 144, 146, 148, precisely defines the angular position of the rotor windings at which the output therefrom will null. One method of producing a command in accordance with the position of stepping switches is shown in the copending application of Herbert M. Fuldrer, Serial No. 52,992, filed August 30, 1960 and entitled Trigonometric Store. Thus the position of the stepping switches produces a predetermined position command signal to effect operation of the wheelhead position control motor WPCM (FIGS. 14A, 14B).

The setting of dials 198 connects one contact of each stepping switch to the ground line 1LL through contacts of relay 17CR (picked up in dials operation) by dials wipers 198A, 198B, 198C, 198D, 198E and 198F, each positioned selectively by the respective dials 198 (FIG. 14A) of each Y axis, or wheelhead position, switch (238L through 243L). After this setting is made, the precycle

setup switch SW10 (FIG. 11C, 73L) is momentarily closed to pick up relays 19CR (73L) and 19ACR (75L) through contacts of relay 33CR, which is energized with the wheelhead in the retracted position, and normally closed contacts of relays 10CR and 16CR. Relays 19CR and 19ACR latch around contacts of switch SW10 through contacts of relay 19CR. When relay 19CR picks up, relay 22CR (80L) will be energized through home closed contacts 8SS and home closed contacts 1ESS if stepping switches 8SS (FIG. 11D, 105L) and 1ESS (FIG. 11C, 81L) are in their home positions. If they are not at home, a ground is on stepper 1ESS through the interrupter contacts of 1ESS, relays 19CR and 22CR and the home opened contacts of stepper 1ESS (shown at location 81L in the home position condition). If the switch 1ESS is not in the home position so that the home contacts 1ESS (81L) are closed, the stepping motor of the switch 1ESS is then energized and begins to move. As it begins to move, the interrupter contacts 1ESS INT (81L) open and the motor is deenergized. This energizing and deenergizing results in one step of movement. After the step, the contacts 1ESS INT again close and the stepping motor is again energized, and then deenergized. Another step is effected. This stepping continues until stepping switch 1ESS is in the home position and home contacts 1ESS open.

Stepper 8SS (FIG. 11D, 105L) also has a ground through contacts of relays 19ACR and 22CR, interrupter contacts 8SS INT of stepper 8SS, and home opened contacts of stepper 8SS. Stepper 8SS steps home the same way that stepping switch 1ESS steps home. When both steppers 1ESS and 8SS are home, relay 22CR (FIG. 11C, 80L) picks up through contacts of relay 19CR and stepping switches 1ESS and 8SS, and latches. The home position contacts of each bank A, B, C, D, F, and E of master stepping switch 1ESS are shown in FIG. 12A at 222L. With the master stepping switch in the home position relay 23CR (FIG. 11C, 83L) is picked up through the interrupter contacts of stepping switch 1ESS. When relay 23CR is picked up, the relay STR-CR (FIG. 12A, 221L) is picked up through contacts of relay 17ACR and 23CR. When relay STR-CR is picked up, the stepping switch motor 1ESS (FIG. 11C, 81L) is energized through contacts of relays 22CR, STR-CR, conductor 12LL, and contacts of relays 17ACR and 23CR (FIG. 12A, 221L). The master stepping switch begins to move and the interrupter contacts thereof (FIG. 11C, 81L) are opened to drop relay 23CR (83L). When relay 23CR drops, relay STR-CR (FIG. 12A, 221L) drops and the master stepping switch motor 1ESS (FIG. 11C, 81L) is deenergized. The master stepping switch wiper contacts W1, W2, W3, W4, W5, W6 are moved in unison to the next set of stepping switch contacts at 223L on the banks A, B, C, D, F, E. The master stepping switch is momentarily stationary and the interrupter contacts thereof are again closed to cause relay 23CR (FIG. 11C, 83L) to pick up since conductor 12LL is connected to the stepping switch bank C (FIG. 12A) at position 223L. The stepper is again moved one step through a pulse to the master stepping motor 1ESS by operation of relay 23CR. Since the C bank of the master stepping switch 1ESS is connected to conductor 12LL from position 222L through position 237L thereon, the wiper contacts W1, W2, W3, W4, W5, W6 (FIG. 12A, 222L) will be moved rapidly in a stepping motion to the first wheelhead store, or Y axis filling position, (FIG. 12C, 238L).

The movement of the wipers W1, W2, W3, W4, W5 and W6 is now controlled through the contacts of the stepping switch Y1SS (FIG. 12C, 238L) and banks C and D of the master stepping switch 1ESS in cooperation with contacts of relay 23CR. Corresponding contacts of the two banks Y1A and Y1B in switch Y1SS (and in the other Y axis switches Y2SS, Y3SS, Y4SS, Y5SS, Y6SS) are electrically connected. When the wiper contacts of stepping switch 1ESS have moved to reference position

238L, relay 23CR picks up, as contacts 1ESS INT close but relay STR-CR does not immediately pick up. Each dial wiper, such as 198A, connects ground line 1LL to the selected contact in the B bank of the switch, such as Y1B, and therefore also connects ground line 1SS to the corresponding contact of the other bank Y1A. This ground furnishes the feed back signal to the master stepper to cause relay STR-CR to be picked up to deenergize the master stepping switch motor 1ESS. Until stepper Y1SS (FIG. 12C, 238L) has moved its wiper contacts W7 and W8 to the grounded contacts, relay STR-CR does not pick up. Stepper Y1SS is connected through its own interrupter contacts Y1SS INT (FIG. 12C, 238L) to ground line 1LL. The stepper Y1SS is connected to 48 volts on the other side through bank A, wiper contact W1 (now moved to position 238L from position 222L, FIG. 12A), contacts of relays 17ACR and STR-CR, and line 3LL. The wiper contacts W7 and W8 (FIG. 12C, 238L) of the stepper Y1SS are advanced in unison on the stepping switch banks Y1A and Y1B of contacts by the make and break action of the interrupter contacts of stepper Y1SS (238L) until the wiper W7 finds the grounded contact determined by the setting of the dials wiper 198A. When wiper W8 of stepper Y1SS moves onto the grounded contact of bank Y1A, relay STR-CR picks up through contacts of relay 17CR, bank C of master stepping switch 1ESS, and wiper W8 of stepping switch Y1SS. This opens the normally closed contact (221L) of relay STR-CR and the stepper Y1SS is isolated from 48 volts. The master stepper 1ESS (FIG. 11C, 81L) is energized and its wipers begin to move, the contacts 1ESS INT (81L) open, and relay 23CR is dropped. When relay 23CR is dropped, conductor 12LL is no longer grounded through contacts of relays 17ACR and 23CR (FIG. 12A, 221L) and the motor of the master stepping switch 1ESS is deenergized and the wiper contacts W1, W2, W3, W4, W5, W6 are moved to the position, 239L, where the stepper Y2SS is energized and stepped until the dial set ground is found.

The Y axis steppers are all operated to put them in positions to connect a predetermined position command signal, corresponding to the setting of dials 198, at the wheelhead position error synchros 144, 146, 148 (FIG. 14A). When all of the Y axis steppers, Y1SS, Y2SS, Y3SS, Y4SS, Y5SS, Y6SS (FIG. 12C) are positioned the master stepper wiper contacts W1, W2, W3, W4, W5, W6 move to position 24L where bank C is connected to conductor 12LL to effect movement of the wiper contacts immediately to position 245L. Relay 10CR (FIG. 11D, 103L) is picked up as a ground is connected to conductor 18LL from bank D (FIG. 12C, 245L) through the wiper W4 and contacts of relay 17BCR. This energizes 1ESS through contacts of relay 10CR, conductor 12LL, contacts of relays 17ACR and 23CR, (FIG. 12A, 221L). When relay 10CR picks up, relays 19CR (FIG. 11C, 73L) and 19ACR (75L) are dropped. As relay 19ACR drops its contacts at (FIG. 11D, 103L) open and relay 10CR drops. Relay 22CR (80L) is deenergized, and the master stepper 1ESS (81L) is deenergized to step to the next position (not shown), the contacts of which are not connected in circuit.

While the master stepper wiper contacts are at 238L, 239L and 240L, the relay 72CR is picked up. In those positions, the contacts of bank E are connected to the grounded wiper W6, a bridging type wiper that makes with the next contact before breaking with the present contact. Therefore the relay 72CR is picked up through the E bank and wiper contact W6. When relay 72CR is picked up, the contacts thereof (FIG. 14B) connect the output of the wheelhead position control motor amplifier 160 to ground through resistor 160R. The output of the modulator 158 (FIG. 14A) is also shorted to ground through contacts of relay 72CR when relay 72CR is picked up. This disables the wheelhead position control motor WPCM (FIG. 14B) while the first three Y axis

steppers Y1SS, Y2SS, and Y3SS are being positioned. When the wiper W6 moves on to position 241L, the relay 72CR is dropped and the wheelhead position control motor is operated by the output from the set of stepping switches 162 (FIG. 14A). The wheelhead begins to move to a predetermined position corresponding to the dial setting, the wheelhead completing its movement after master stepping switch 1ESS has finished stepping through the position at 244L.

10 In dials positioning of the wheelhead, relay 20CR (FIG. 11C, 76L) is picked up through contacts of the relays 31CR, 32CR, and 16CR and the normally closed contacts of switch SW10. Therefore, when the wiper contact W6 is moved to the bank E contact at 243L (FIG. 12C) the relay 73CR (243L) is picked up through the wiper contact W6 and the bank E of the master stepping switch. Relay 73CR then latches through contacts of relays 73CR and 20CR.

When the wheelhead approaches its final position and 20 is under control of the fine synchro 148, and both contacts 150A and 150B (FIG. 11E, 127L, 128L) in the synchronizing network, which open when synchros 144, 146, respectively, are disconnected, are now open. The relay 26CR (FIG. 11E, 127L) is dropped, having been 25 picked up when the command signal was first introduced into the amplifier 150. Relay 27CR (FIG. 11E, 129L) is not picked up since the contacts of relay 17CR (129L) are opened and there is no ground thereon. Since relays 26CR and 27CR are dropped and relay 73CR is picked up, 30 relays 28CR (132L) and 29CR (133L) are both picked up. During the time that relay 19CR (73L) was picked up, relay 53CR (FIG. 11G, 196L) was picked up through contacts of relays 16CR, 19ACR, and 39ACR, and latched through its own contacts.

35 The cycle start switch SW5 may now be closed to start the grinding cycle by putting a ground on conductor 8LL (FIG. 11B, 59L) through contacts of relays 16CR, 28CR, 29CR, and 53CR and the cycle start switch SW5. The selected grinding cycle proceeds automatically as described 40 above. Once the grind cycle has started, the dials 198 may be reset or left the same, depending on the diameter to be ground in the next grinding operation. Upon completion of the grinding operation, the pre-cycle setup switch SW10 (FIG. 11C, 73L) is again closed to position the 45 wheelhead if a different diameter is desired. Otherwise, the cycle may be immediately begun again.

Electrical Operation Tape Control

The grinding machine described may be automatically 50 operated through one of five types of tape controlled operation cycles: plunge grind, coarse traverse grind, fine traverse grind, coarse true, and fine true. The selection of operation type is made from a block of numerical data stored in a discrete portion 61a (FIGS. 2, 6) of a punched tape 61 in the information storage mechanism. The tape portion 61a also furnishes table and wheelhead position information to effect proper relationship therebetween before the cycle of operation is started and information for both positions between which the table moves in the 55 traverse grinding and truing operation. The information mechanism operates automatically to index the tape so that a series of selected operations (which may comprise any mixture of the five types of operation) can be performed on a workpiece automatically without interruption.

Before the tape control operation is commenced, a reference position of the wheelhead 19 must be established 60 to correspond with both the diameter of the grinding wheel and the predetermined reference diameter position 70 command signal produced by the information storage mechanism. To establish the wheelhead reference position, the dials system 198 is hand set to the reference diameter and the wheelhead is automatically moved to a position on the wheelhead slide 20. The wheelhead advance switch SW3 (FIG. 11B, 60L) is momentarily closed 75

to move the wheelhead to the forward end of its rapid advance stroke. The wheelhead position is adjusted by manual operation of the wheelhead handwheel 124 to move the wheelhead until it is in position to just contact the diamond point 164 of the truing tool 22. The knob 124a is pulled forward to disengage the handwheel and the handwheel is adjusted to engage the positive stop 128. The grinding wheel 18 is trued by manual operation of the table: The switch SW4 (FIG. 11B, 60L) is momentarily opened after truing is completed to retract the wheelhead. The wheelhead is now in the reference position corresponding to the reference diameter position command signal and the diameter of the grinding wheel.

Selector switch SW1 (FIG. 11B, 67L) is placed in the tape position and selector switch SW2 (53L) is inoperative since relay 17CR (FIG. 11C, 68L) is not energized when switch SW1 is in the tape position. The tape 61 is advanced between the two contacts (one of which is a pecker contact periodically urged to contact the other contact when an opening in the tape permits) of the respective pairs of contacts 59a, 59b, 59c, 59d, 59e, 59f, 59g (FIG. 11D, 92L-98L) of reader 59 to its correct alignment in the reader by operation of the tape advance switch SW11 (71L) which energizes relay 18CR (72L) through contacts of relays 17CR, 19CR, and 10CR to energize the tape reader clutch 59h (FIG. 11C, 86L). The tape advances until relay 10CR (FIG. 11D, 103L) is energized by a line of tape which allows contacts 59g (98L) to close to signal proper tape alignment. When relay 10CR is energized, relay 18CR is deenergized to deenergize clutch 59h and stop the tape.

With the tape properly aligned, the pre-cycle setup switch SW10 (73L) is manually closed momentarily. Relays 19CR (73L) and 19ACR (75L) are picked up through contacts of relays 16CR, 10CR, and 33CR. Relays 19CR and 19ACR latch through their own contacts around switch SW10. Relay 21CR (77L) is also picked up through contacts of the relay 19CR and relay 21CR is latched through contacts of relay 75CR and 21CR and normally closed stop switch SW17. Relay 21CR remains latched until an in-cycle stop is coded in the tape to pick up relay 75CR (FIG. 12C, 244L), at the end of a cycle, to stop operation of the machine, or until switch SW17 is opened to stop the machine cycle. Also when switch SW10 is released, relay 20CR (76L) is picked up through contacts of relays 31CR, 32CR, and 16CR.

As relay 19CR picks up, the master stepping motor 1ESS (81L) is energized and deenergized as in the dial's operation until it has stepped to its home position and relay 22CR is picked up. The master stepping switch banks, A, B, C, D, E and F (FIG. 12A, B, C) and its wiper contacts W1, W2, W3, W4, W5, and W6 (FIG. 12A, 222L) are the mechanism which controls the tape reading operation and the indexing of each presettable portion 61a (FIGS. 2, 6) of the tape 61 through the reader 59 in steps of one line of holes at a time. When relay 23CR is picked up, the tape reader clutch 59h (FIGS. 11C, 86L) is connected to 48 volts at line 3LL and ground at 1LL through contacts of relays 22CR, 20CR, 23CR, 24CR, and 3CR. The tape reader 59 includes a rotary timing cam (not shown) which makes one revolution per line of tape read. At the 30° point in its rotation, the cam closes contacts 59k (90L) to pick up relay 24CR (90L). When relay 24CR is picked up, the reader clutch 59h is deenergized. The period of time from the instant that relay 23CR picks up until the cam has rotated to 30° results in a pulse to the reader clutch sufficient to advance the tape just one line. Relay 24CR remains picked up until the relay 23CR is dropped again. Relay 24CR is latched through its own contacts (91L) around the cam controlled contacts 59k which are opened after the timing cam has rotated through 160° from the start of the read cycle when relay 23CR picked up.

After the reader has been pulsed and a line of holes 61b

of the tape 61 is passed to a position between the reader pecker contacts 59a through 59g (FIG. 11D, 92L through 98L) a predetermined combination of decoder relays 10CR, 1CR, 2CR, 2ACR, 4CR, 8CR and CKCR (103L) are picked up and latched through contacts of relays 19ACR, 3CR, and 23CR and their own contacts. The stepping switch bank of contacts 4SSB, X1A, X2A, X3A, X4A, X5A, X'1A, X'2A, X'3A, X'4A, X'5A, Y1A, Y2A, Y3A, Y4A, Y5A, and Y6A (FIGS. 12A, 12B, 12C, 25L through 243L) each have contacts which are connected, respectively, to the ten conductors 1 through 10 in the decoder network shown at FIG. 11E, 117L through 126L. The network is controlled by relays 1CR, 4CR, 2CR, 8CR, and CKCR, through contacts shown in the drawing FIG. 11E, 117L through 126L under the relay designation. If one or more of these relays is energized through the pecker contacts, one and one only of the conductors 1 through 10 (and hence one and one only of the contacts on each of the stepping switch banks connected to the decoder network) is connected to line 4LL which is connected to ground line 1LL through normally closed contacts of relay 17CR (FIG. 11C, 71L). In order to minimize errors which would result if one relay failed to pick up, the system will respond only when relay 25CR is picked up, which occurs only on energization of an odd number of the relays 1CR, 4CR, 2CR, 8CR and CKCR (or energization of relay 10CR). This is controlled through the parity network (FIG. 11D, 103L through 114L) by contacts of these relays shown under the relay designation. When relay 25CR is picked up, a ground is placed on the master stepping switch motor 1ESS (FIG. 11C, 81L) through contacts of the relay 22CR and STR-CR (which picks up through contacts of relay 17ACR, banks B and C, and contacts of relay 25CR, (see FIG. 12A, 220L to 223L) and conductor 12LL. As the master stepping switch 1ESS is energized and begins to move, its interrupter contacts 1ESS INT at 81L (FIG. 11C) are opened and relay 23CR is dropped and the decoder relays (103L) are dropped since they are latched through contacts of relay 23CR. When the decoder relays are dropped relay 25CR (111L) is dropped. The relay STR-CR (FIG. 12C, 221L) is also dropped. The master stepper 1ESS (FIG. 11C, 81L) also is deenergized and the wiper contacts thereof are moved to the next position (223L). Relay 23CR is again picked up and the reader clutch 59h (86L) is pulsed again. A new line of tape is moved under the reader pecker contacts 59a through 59g and relay 25CR is not picked up until a new combination of decoder relays is picked up. If another valid line is read (that is, a line to energize an odd number of relays) relay 25CR (FIG. 11D, 111L) picks up and the master stepping switch motor 1ESS (FIG. 11C, 81L) is again stepped in the manner described. The master stepping switch is moved in this way until the wiper contacts W1 through W6 (FIG. 12A, 222L) have moved to the contacts of the stepping switch banks at reference line 225L.

The line of tape read by the reader 59 while the wiper contacts W1 through W6 are at 225L determines the type of operation to be performed in the next grinding cycle. While in position 225L, the wiper contact W6 connects relay 76CR to ground through the bank E and relay 76CR is energized. The ground is removed from the wiper W9 at the bank of contacts 4SS-A of stepping switch 4SS at 187L (FIG. 11G) while the wiper contact W10, which is mechanically connected to wiper contact W9, of stepping switch 4SS (FIG. 12A, 225L) is seeking the grounded contact of the bank 4SSB of contacts (FIG. 12A, 225L). Stepping switch motor 4SS (225L) has control voltage applied to it from the master stepper 1ESS bank A through contacts of relays 25CR and STR-CR and its wiper W10 contact will step around until it finds a ground on one of its own 4SSB contacts. One of the 4SSB contacts of stepper 4SS (FIG.

12A, 225L) is grounded by the decoder circuit (FIG. 11E, 117 through 126L) by a combination of the reader relays (FIG. 11D, 103L) as determined by the line of holes in tape 61 being read while the master stepping switch is at position 225L (FIG. 12A). When the ground is found, relay STR-CR is picked up through the grounded contact of stepping bank 4SSB, contacts of relay 17ACR, and wiper W2. The master stepper 1ESS (FIG. 11C, 81L) is energized and the wipers W1 through W6 begin to move. As the master stepper moves, relay 23CR (FIG. 11C, 83L) is dropped and the latch is removed from the reader relays (FIG. 11D, 103L) and they are dropped. The parity relay 25CR also drops.

When the master stepper reaches its next position, relay 23CR is picked up and the reader clutch is again pulsed. A new line of tape is read and a new combination of reader relays picked up and latched. The line of information determines whether the wheelhead moves to position before the table moves to position or whether the table moves before the wheelhead moves. Normally the table moves first, so relay 69CR (FIG. 12A, 226L) picks up through the contacts of relays CKCR, 1CR and 77CR (226L) the latter of which picks up through the parity check relay 25CR and the stepper relay STR-CR as the master stepper moves to position 226L. When relay 69CR is up it latches through contacts of relays 69CR, 70CR, and CKCR. The master stepping switch 1ESS (81L) is again pulsed through contacts of relays 22CR and STR-CR, the latter of which is picked up through contacts of relay 17ACR, wiper contact W2, bank B, contacts of relay 69CR, and contacts of relay 25CR.

When the master stepper gets to the position corresponding to location 228L, the reader clutch is again pulsed as relay 23CR is picked up again and a new line of tape information is presented to the pecker contacts for reading. The line is the first portion of the table position, or X axis, information. The stepping switch motor X1SS (228L) has control voltage applied through contacts of the relays 25CR and STR-CR and wiper W1. Stepping switch motor X1SS is stepped by operation of its interrupter contacts X1SS INT (228L) which are opened when the stepper wiper W11 is moving and closed when it stops. Wiper W11 is moved to a position determined by the reader relay combination produced by the tape information in the reader and the effect that this combination has on the decoder circuit (117L through 126L, FIG. 11E). The movement of wiper contact W11 of stepping switch X1SS, as well as movement of the wiper contacts of stepping switches X2SS, X3SS, X4SS, X5SS, which comprise the set of stepping switches 58, serve to position other wiper contacts (not shown) mechanically connected, thereto and produce a predetermined position command signal, depending on their respective positions, in the same manner as the set of Y axis stepping switches 162. After the stepper X1SS has moved to the proper position, relay STR-CR (FIG. 12A, 221L) picks up through a contact of stepping switch bank X1A, wiper contact W2, and contacts of relay 17ACR and causes the master stepping switch motor 1ESS (FIG. 11C, 81L) to be pulsed to move to the next position, 229L, FIG. 12C.

While the master stepper is reading in positions corresponding to reference locations 228L, 229L, and 230L (FIGS. 12A and 12B), relay 71CR (FIG. 12B, 231L) picks up from a ground in bank E of the master stepping switch through the normally closed contacts of relay 17ACR in its circuit. When relay 71CR is picked up, the table control motor TCM (FIG. 13C) is disabled and cannot run since the output of the table control motor amplifier 44 is passed to ground through resistor 44R (FIG. 13C). When the master stepper moves on to the next position (231L), relay 71CR drops and the table control motor begins to operate to effect the proper positioning of the table prior to starting the grinding

operation. Relay 71CR is dropped when the master stepping switch moves to the next position since there is no latch on relay 71CR. Thus, positioning of the table begins before positioning of the wheelhead is begun.

If, when the master stepper was in position 226L (FIG. 12A), relay 70CR (227L) had been picked up through contacts of relays CKCR, 2ACR, 77CR and 20CR, relay 71CR (FIG. 12C, 231L) would be latched initially through contacts of relays 17ACR, 71CR, 34CR, 69CR and 73CR, and subsequently, through contacts of relays 17ACR, 71CR, 34CR, 29CR and 76CR. The latch would not be removed until the wheelhead was in position when relay 29CR is picked up through contacts of relays 17BCR and 26CR. After the master stepper contacts W1 through W6 have moved to position 238L (FIG. 12C) and the wiper contacts W7 and W8 of the stepping switch Y1SS have been positioned, a position error signal is then present in the two channel amplifier 150 (FIG. 14A) and relay 26CR (FIG. 11E, 127L) is picked up, to drop relay 29CR (133L). Therefore the ground through contacts of relays 17ACR, 34CR, 29CR and 70CR to relay 71CR (FIG. 12B, 231L) determines when the table control motor disable condition will be removed. Thus, if relay 70CR, instead of 69CR, has been picked up, the wheelhead would be positioned before the table control motor TCM (FIG. 13C) would be able to run. If, however, relay 69CR is picked instead of relay 70CR, the table is moving during the time that the final portions of the X axis first table position stores are filled since the normal condition of table before wheelhead movement is occurring.

The master stepping switch moves to the X', or second table position, stores. If two table positions are required, the X' stores will be filled (that is, the stepping switches X'1SS, X'2SS, X'3SS, X'4SS, and X'5SS comprising the set of stepping switches 69, will be positioned to produce a position command signal) in the same way that the first table position stores (set 58 of the stepping switches) are filled. If the operation is a plunge operation where a second table position is not used, a tabulation or tab may be coded such that the tab stepping switch 8SS (FIG. 11D, 105L) has stepped to connect contact T to ground. That contact is connected to the bank F of the master stepper (FIG. 12B) in all of the X' positions (FIGS. 12B, 12C, 233L through 237L). Therefore if the tab stepping switch has placed a ground on contact T, when the master stepper steps onto the X' stores positions it will immediately step to the next position without changing the X' stores. The tab contacts R, S, T, U, and V (105L) are to effect rapid movement of the master stepping switch, without effect on the circuit, through the stores positions for: the operation type position (FIG. 12A, 225L), the X positions (FIGS. 12A, 12B, 228L through 232L), the X' positions (FIGS. 12B, 12C, 233L through 237L) the Y positions (FIG. 12C, 238L through 243L), and the code stop position (FIG. 12C, 244L), respectively.

To move the wiper contact W12 to the contact T of the bank of 8SS contacts (FIG. 11D, 105L) a tab sequence must be coded into the tape when the master stepping switch wiper contacts move to the position 233L (FIG. 12B). The tab sequence includes a combination of decoder relays (103L) to pick up relay TCR (108L) through a combination of the parity check circuit contacts (108L through 114L). When relay TCR is picked up, the stepping switch motor 8SS (105L) is energized through contacts of relay TCR. When the stepping switch motor 8SS is energized the contacts of the stepping switch 8SS (115L) are closed and relay 3CR picks up. When relay 3CR is picked up, the latch is removed from the decoder relays and they are dropped. Relay 24CR (FIG. 11C, 90L) is also dropped if it is up and the reader clutch 59h is deenergized. The tab relay TCR is dropped when the decoder relays are dropped, and as a result, the 75 stepping switch motor 8SS (FIG. 11D, 105L) is deener-

gized. When the stepping switch motor 8SS is deenergized the wiper W12 is advanced one position. Relay 3CR is also dropped when the stepping switch motor 8SS is deenergized. When relay 3CR is dropped the clutch is immediately energized again and the tape is advanced one line. Another tab sequence is coded in the tape and the wiper W12 is advanced one position again. A series of tab sequences is coded into the tape to effect movement of the wiper W12 to make with the contact T. During the time that the wiper W12 is being moved, the wiper contacts W1 through W6 of the master stepping switch are at position 233L and are not moved. The stepping of the motor of stepping switch 8SS occurs very rapidly since only the tape and the wiper W12 are being advanced.

As soon as the wiper W12 makes with contact T, a ground through the contacts 1ESS INT (FIG. 11C, 81L) and conductors 21LL is placed on contact T. Contact T is connected to the bank F contacts at 233L through 237L (FIGS. 12B, 12C). When the contact T is grounded, the relay 5CR (FIG. 12A, 222L) is picked up through wiper W5. When relay 5CR is picked up, the master stepping switch motor 1ESS (FIG. 11C, 81L) is energized through contacts of relay 5CR. The interrupter contacts thereof, 1ESS INT (81L), are opened as the master stepper begins to move its wiper contacts. The relay 5CR and the master stepping switch motor are immediately deenergized and the wiper contacts W1 through W6 are advanced to the next position, 234L (FIG. 12B). The interrupter contacts 1ESS INT at 81L (FIG. 11C) are again closed and a ground is again on the contact T connected to the bank F contact at 234L to cause relay 5CR to pick up again. The master stepping switch wiper contacts are moved rapidly to the next position 235L. The rapid movement of the wiper contacts continues until the master stepping switch wiper contacts have moved to position 238L (FIG. 12C). During the time that these wiper contacts are being moved, the relay 3CR picks up through contacts of relay 5CR each time that relay picks up. When relay 3CR is picked up, the reader clutch 59h cannot be pulsed and the tape does not advance during movement of the master stepping switch wipers through positions 233L through 237L.

After the master stepping switch has moved to the position 238L the stepping switch Y1SS motor is energized and the wipers W7 and W8 are positioned as the X axis stores stepping switches X1SS through X5SS were positioned, a selected contact of the bank of contacts Y1A being connected to ground through operation of the decoder relays and the decoder circuit. The stepping switches Y2SS, Y3SS, Y4SS, Y5SS, and Y6SS are also positioned in this manner. Thus, with tape control, the Y axis stepping switches are automatically positioned in accordance with the digital information on the tape instead of by the dials 198 as in dial control. When the wiper contacts W1 through W6 are on the first three positions of the Y stores (238L, 239L, 240L), the relay 72CR (239L) is picked up from a ground on the bank E of the master stepping switch through wiper W6. When relay 72CR is up, the wheelhead position control motor WPCM (FIG. 14B) is disabled as in dial controlled operation and will not operate. When the master stepping switch steps to the position corresponding to reference location 241L, the relay 72CR is dropped and the wheelhead begins to move to its proper position. It should be noted that if the table is not in position (in a table before wheelhead operation) the relay 72CR is latched through contacts of relay 17BCR, 72CR, 28CR, and 69CR. Relay 72CR remains latched until the table is in position and relay 28CR is picked up. The last stepping switches of the Y stores are positioned, and the master stepping switch wiper contacts move to the last position on the stepper switch 245L and a ground is placed on conductor 18LL connected to relay 10CR (FIG. 11D, 103L) which is picked up to signal the end of a block of information. The sets of stepping switches

58 and 162 are now positioned from the block of digital information obtained from the portion of tape that has passed under the reader pecker contacts during the time that the master stepping switch 1ESS was inactive to move its wiper contacts from the home position 222L to position 245L.

When relay 16CR is picked up at the end of a reading cycle, relays 19CR (FIG. 11C, 73L) and 19ACR (74L) are deenergized. Relay 22CR (80L) then drops. When both the wheelhead and table are moved to position by the wheelhead and table motors respectively, relays 28CR (FIG. 11E, 132L) and 29CR (133L) are picked up through contacts of relays 73CR (picked up and latched when wipers are at position 243L (FIG. 12C)) and 26CR and 27CR (FIG. 11E, 127L, 129L) which are dropped when the wheelhead and table are in position. Relay 53CR (FIG. 11G, 196L) is up, having latched when relay 19CR was still up. The cycle start switch SW5 is now closed, and the grind cycle selected from the tape by means of wiper contact W9 (FIG. 11G, 186L) proceeds. If the cycle selected is for a plunge grind, it proceeds as described in the automatic plunge grind operation until the wheelhead is retracted and relay 33CR (142L) is energized. Either of the traverse cycles might be selected. They too will proceed to completion until the wheelhead retracts and relay 33CR is energized.

At the end of a numerically selected grind cycle when relay 33CR picks up, relay 31CR (FIG. 11E, 139L) is picked up through contacts of relays 33CR and 21CR (77L, FIG. 11C, up from the start of the tape controlled operation and latched until a stop is coded in the tape). The capacitor CAP1 in the circuit of relay 32CR (FIG. 11E, 140L) holds that relay up long enough with relay 31CR to cause relays 19CR and 19ACR (FIG. 11C, 73L, 75L) to be energized again through contacts of relays 31CR, 32CR and 10CR. The master stepper begins another reading cycle and the stores are refilled as another portion of tape is indexed through the reader.

40 The next grind cycle is started automatically when the table and wheelhead have moved to position. Relay 39CR is picked up and latched during the first cycle and does not drop until the cycle stop switch SW6 (FIG. 11F, 152L) is opened, or until a stop is coded on the in cycle stop switch SW17 (77L) is opened to drop relay 21CR. Therefore, when the wheelhead and table are in position, the cycle start switch SW5 (FIG. 11B, 58L) is bypassed through contacts of relays 16CR, 28CR, 29CR, 53CR, 39CR, 19CR and 17CR.

45 Should the next cycle selection be for a coarse traverse grind operation, wiper W9 of the stepping switch 4SS (FIG. 11G, 187L) would be positioned to cause relay 67CR (190L) to be energized. When relay 67CR is up, relay 57CR (193L) is energized and up. The traverse cycle will start with the feed out and rapid in as previously described. At the end of the rapid infeed, relay 34CR (FIG. 11E, 143L) will be picked up. Now relay 54CR (FIG. 11G, 201L) picks up through contacts of relays 67CR, 58CR, 64CR, 52CR, 34CR, and 27CR. When relay 54CR is picked up, the X' set of stepping switches 60 (FIG. 13A) is connected to the table position error synchros 62, 64, and 66 and the X set of stepping switches 58 is disconnected therefrom. Thus, when the sets 58, 60 are switched, a table position command signal is connected from the information storage mechanism to the table position error synchros 62, 64, and 66 and a position error signal is produced therefrom. Relay 27CR (FIG. 11E, 129L) picks up. When relay 27CR picks up, the ground on relay 71CR (FIG. 12B, 231L) through conductor 17LL (FIG. 11G, 198L) is removed and the table control motor TCM (FIG. 13C) is allowed to run to direct the table to the X' position. When the table has moved to the X' position, relay 27CR is dropped and relay 71CR (FIG. 12B, 231L) picks up through contacts of relays 27CR,

16CR, 19ACR, and conductor 17LL (FIG. 11G, 199L). The table is stopped.

A micro positioner 192 (FIGS. 2, 13C) is connected between the table error amplifier 32 and the table servo valve 28. The positioner is actuated by the electro magnetic force produced in its windings 194, 196 (FIG. 11B, 39L, 41L) when the table control motor is energized. Relay 106CR (FIG. 11B, 39L) is picked up as the torque arm 192a swings to connect relay 106CR to ground through contacts of relays 17CR, 64ACR, 27CR as the table is moving left, and relay 107CR (41L) is picked up in a similar manner if the table is moving to the right. Contacts of relays 106CR and 107CR in the pickfeed timer 2TR are positioned such that timer 2TR is operated at the end or ends of the table stroke in accordance with the setting of the selector switch SW8. Contacts of relays 106CR and 107CR are also included in the table tarry timer to cause operation in accordance with the selected settings of either potentiometer 8POT or 9POT which may be set to produce a separate tarry time for each end of the table stroke.

When relay 27CR drops, the micro-positioner 192 (FIG. 11B, 40L) goes to neutral. Relays 64CR (FIG. 11H, 203L), 64ACR (206L), and 63CR (207L) are picked up through contacts of relays 17CR, 27CR, 64CR, and either relay 108CR or relay 109CR. One of the relays 108CR (FIG. 11B, 45L) or 109CR (51L) is up when relay 27CR is dropped and before relay 64CR is picked up since either relay 106CR (39L) or relay 107CR (41L) is always picked up during table travel. When relay 64CR is energized, the pickfeed timer 2TR (FIG. 11A, 24L) and the table tarry timer 3TR (28L) are set off. The pickfeed potentiometer 13POT circuit is tied to the wheelhead control motor WCM (FIG. 14B, C) by relay 63CR. The wheelhead pickfeeds forward and stops when timer 2TR times out. The table continues to tarry until timer 3TR times out. Relays 63CR, 64CR and 64ACR are all deenergized.

At the same time that relay 64CR is picked up, relay 54CR is dropped and the X set of stepping switches 58 (FIG. 13A) is connected to the table position error synchro replacing the X' set 60. A new position command signal is fed into the synchro elements to produce a position error signal at the three channel amplifier 68 (FIG. 13A). When relay 64CR drops, relay 71CR (FIG. 12B, 231L) is dropped since conductor 17LL is not grounded (FIG. 11G, 198L). The table control motor now operates at a rate determined by the setting of 3POT (FIG. 13B) to move the table to the left or X position. Relay 27CR is picked up. When relay 27CR is up, the micro-positioner is re-energized and assumes a position corresponding to the feed left position (assuming the X position is at the left end of the table stroke). Relay 106CR is picked up. When the table reaches the X position, the wheelhead will pickfeed, the table will tarry, and then the table will begin to move right. This reciprocation of the table and wheelhead pickfeed will continue until the positive stop is engaged by the wheelhead handwheel 124 (FIG. 14C). Relay 35CR (FIG. 11E, 144L) is then energized through contacts of relays 30CR, 67CR, and the contacts of limit switch 1LS.

Prior to the time when relay 35CR is up, stepping switch 7SS (FIG. 11H, 210L) has stepped home. The table continues to reciprocate between the X and X' positions and each time that the table reverses direction of movement, relay 71CR (FIG. 12B, 231L) is picked up and then dropped. Each time relay 71CR drops, the stepper 7SS steps once. When the stepper 7SS has stepped to the position set on the dead pass selector SW9 (213L), relay 65CR (213L) is picked up. Relay 30CR (134L) drops and the wheelhead is retracted to pick up relay 33CR (142L). The reader clutch is pulsed, the master stepper energized and a new portion of tape is read to refill the information stores.

If the tape information directs the machine to go

through a fine traverse grind operation, relay 58CR (FIG. 11G, 191L) will be picked up by the wiper contact W9 at the start of the grind operation. The grind cycle will proceed as in the plunge cycle until the fine feed cam closes limit switch 2LS and relay 36CR (FIG. 11F, 148L) is picked up. The traverse cycle will commence as described with the table moving between the X and X' positions. The positive stop will be engaged by the handwheel, the dead passes taken, and the wheelhead rapidly retracted to again pick up relay 33CR to effect another reading cycle.

The tape may now direct a coarse truing operation. When the truing operation begins after the reading cycle, the wheelhead advances forward in rapid motion immediately. This occurs since relay 55CR (FIG. 11G, 188L) was picked up through wiper contact W9 by action of the cycle selection stepper 4SS (187L) and in turn caused relay 52CR (194L) to be picked up. When the wheelhead and table are in position after the tape reading cycle, relays 28CR and 29CR (FIG. 11E, 132L) are picked up. The rapid advance relay 30CR (FIG. 11E, 134L) is then energized through contacts of relays 39ACR and 52CR. The handwheel is against the positive stop and relay 35CR (144L) is energized. The stepping motor 6SS (FIG. 11G, 163L) is now energized through contacts of relays 52CR, 49CR, 35CR, 34CR and 46CR. As stepper 6SS is energized, relay 46CR is picked up through contacts of relays 52CR, 49CR, 35CR, 34CR, 47CR, and 17CR and contacts of stepper 6SS. Relay 46CR latches. When relay 46CR picks up, the stepping motor 6SS is driving the ratchet wheel 174 (FIG. 8) to rotate the compensation resolver 166 (FIG. 14C) to effect an increment of movement of the wheelhead. As stepping motor 6SS is deenergized, at the first step, relay 47CR (FIG. 11G, 174L) is picked up through contacts of relays 52CR, 49CR, 35CR, 34CR, 17ACR, 46CR, line 9LL and normally closed contacts of stepper 6SS. Relay 47CR latches. When a relay 47CR is picked up, stepping motor 6SS is energized, being energized through contacts of relays 49CR, 47CR, 48CR, 34CR, 35CR, 52CR. Relay 48CR (178L) is now energized through contacts of relays 52CR, 49CR, 35CR, 34CR contacts of stepper 6SS, 47CR and line 10LL. Relay 48CR latches. When relay 48CR is up, the stepping motor 6SS is deenergized to effect the second step. Thus the wheelhead has been pick fed toward the truing tool in two steps. Relay 49CR (180L) comes up when relay 48CR is energized through the contacts of relays 48CR and 33CR. Relay 49CR being up and latched prevents the stepper 6SS from being energized again at this time. Relay 54CR (201L) is also picked up through relay contacts of 52CR, 58CR, 64CR, 49CR, 34CR, and 27CR. When relay 54CR is up, the table moves from the X position to the X' position as it does in traverse grind operations. The rate at which the table moves is controlled by potentiometer 5POT (FIG. 13B) which controls the speed of the wheelhead control motor during a coarse truing since it is connected into the control motor circuit when relay 55CR is energized. When the table arrives at the X' position, the relay 27CR (FIG. 11E, 129L) is dropped out, relay 64CR (FIG. 11H, 203L) is picked up, the disable relay 71CR (FIG. 12B, 231L) picks up, tarry takes place, and the stepper 7SS (FIG. 11H, 210L) steps one time. If the truing selector switch SW13 (214L) is set for one pass, relay 65CR is picked up and the wheelhead is retracted. If more than one truing pass is selected, the table stores are switched and the stepper 6SS is caused to step twice again when relay 64CR (203L) is energized to effect the sequential energization of relays 46CR, 47CR and 48CR. Relay 49CR remains latched until the truing cycle is completed. Each time the table makes a pass with the truing tool, relay 64CR is energized to effect operation of the compensation stepping motor 6SS. When the preset member of passes have been made, the wheelhead re-

tracts and relay 33CR (FIG. 11E, 142L) is energized. A new portion of tape is read and a new operation begun at completion of the reading cycle.

The tape may select a fine truing cycle and relay 56CR will be energized through wiper contact W9. In fine truing, the cycle proceeds through a first double pickfeed as in the coarse truing cycle, but now relay 50CR (FIG. 11G, 182L) is picked up through contacts of relays 48CR, 49CR, and 56CR after the second step of the stepping motor 6SS. Relay 50CR latches. The table moves from the X position to the X' position after the double step of the stepping motor 6SS. The rate of movement is now controlled by potentiometer 4POT (FIG. 13B) which is connected in circuit by relay 56CR. When the table arrives at the X' position relays 64CR and 64ACR are picked up and stepper 6SS (FIG. 11F, 163L) is energized through contacts of relays 52CR, 64ACR, 51CR, 35CR, 34CR and 46CR. When stepper 6SS is energized, relay 46CR (167L) is picked up through contacts of relays 52CR, 64ACR, 51CR, 35CR, 34CR, 47CR, and 17CR and stepper 6SS. Stepper 6SS is de-energized and steps one time. Relays 47CR (FIG. 11G, 174L) and 48CR (178L) now pick up in succession but the stepper 6SS is not energized again since relay 49CR (180L) is up and latched from the first double pick and relay 55CR is not up. When relay 48CR is up, relay 51CR is energized through contacts of relays 48CR and 50CR. Relay 51CR latches. At the same time that relay 48CR is picked up, relay 64CR (FIG. 11H, 203L) is deenergized and the table control motor is energized and the table is moved back to the X position. This is the last truing pass. Relay 48CR is caused to drop immediately after relay 64CR was dropped. Relay 51CR is still up and latched. Now when the table reaches the X position relay 65CR (213L) is immediately energized through contacts of relays 51CR, 48CR, and 64CR before a truing pickfeed can again take place. Relay 30CR (134L) and 30ACR (136L) are deenergized and the wheelhead is rapidly retracted and a new block of tape is read in preparation for the next cycle.

What is claimed is:

1. In a machine tool the combination comprising a control motor, a synchro transmitter operatively connected to the control motor for rotation thereby, a machine slide, a slide motor connected to the slide for movement thereof, a synchro receiver mechanically connected for rotation corresponding to movement of the slide by the slide motor and electrically connected to the synchro transmitter for production of an error signal, means to control the slide motor in response to said error signal, and a positive stop adapted to terminate rotation of the synchro transmitter after a predetermined rotation thereof.

2. In a machine tool the combination comprising a movable control member, a control motor connectable to the movable control member for movement thereof, a synchro transmitter mechanically connected for rotation corresponding to movement of the movable control member by the control motor, means to control operation of the control motor to establish the extent and rate of movement of the movable control member, a positive stop to terminate movement of the movable control member after a predetermined movement thereof, a movable machine member, a machine motor connected to the movable machine member for movement thereof, a synchro receiver mechanically connected for rotation corresponding to movement of the movable machine member by the machine motor and electrically connected to the synchro transmitter for production of an error signal, and means responsive to said error signal to control said machine motor.

3. In a machine tool the combination comprising a movable control member, a variable speed electric control motor connectable to the movable control member for movement thereof, a synchro transmitter mechanically connected for rotation corresponding to movement of

the movable control member by the control motor, pre-settable means operable in response to movement of the movable control member to determine the extent of movement thereof and to change the speed of the control motor to change the rate of movement of the control member and synchro transmitter, a positive stop to terminate movement of the movable control member after a predetermined movement thereof, a movable machine member, a machine motor connected to the movable machine member for movement thereof, a synchro receiver mechanically connected for rotation corresponding to movement of the movable machine member by the machine motor and electrically connected to the synchro transmitter for production of an error signal, and means responsive to said error signal to control said machine motor.

4. In a machine tool the combination comprising a movable control member, a variable speed electric control motor connectable to the movable control member for movement thereof, a synchro transmitter mechanically connected for rotation corresponding to movement of the movable control member by the control motor, a controller electrically connected to the control motor operable when actuated to change the electrical input thereto to change the speed of the motor, a plurality of limit switches to actuate the controller when operated, pre-settable trip members operable in response to movement of the movable control member to determine the extent of movement thereof and operate said limit switches after predetermined increments of movement of the movable control member, a positive stop to terminate movement of the movable control member after a predetermined movement thereof, a movable machine member, a machine motor connected to the movable machine member for movement thereof, a synchro receiver mechanically connected for rotation corresponding to movement of the movable machine member by the machine motor and electrically connected to the synchro transmitter for production of an error signal, and means responsive to said error signal to control said machine motor.

5. In a grinding machine the combination comprising a rotatable handwheel, a unidirectional variable speed electric control motor, means including a pair of selectively engageable clutches connecting the control motor to the handwheel to move the handwheel in one direction when one of said clutches is engaged and to move the handwheel in the opposite direction when the other of said clutches is engaged, a resolver transmitter mechanically connected for rotation by the control motor corresponding to rotation of the handwheel, a controller electrically connected to the control motor operable when actuated to change the electrical input thereto to change the speed of the motor and the handwheel, a first limit switch to disengage one and engage the other of said clutches when operated to reverse direction of the handwheel and a second limit switch to actuate the controller when operated, a first cam rotatable in accordance with the movement of said handwheel and adjustable relative to said first limit switch to establish the limit of rotation of said handwheel in one direction and a second cam adjustable relative to said second limit switch to establish the extent of rotation of the handwheel at the different speeds thereof in the opposite direction, a positive stop to terminate movement of the handwheel member in said opposite direction, a movable wheelhead having a grinding wheel rotatably mounted therein, a hydraulic motor connected to the wheel head for movement thereof, a resolver receiver mechanically connected for rotation corresponding to movement of the wheelhead by the hydraulic motor and electrically connected to the resolver transmitter for production of an error signal, and a hydraulic servo-valve responsive to said error signal to control said hydraulic motor.

6. In a grinding machine having a table adapted to

support a workpiece and a wheelhead movable towards and away from the workpiece, the combination comprising a reversible fixed stroke rapid advance motor connected to the wheelhead for rapid movement thereof a fixed amount, a reversible feed motor connected to the wheelhead to effect feeding movement thereof, a synchro receiver mechanically connected for rotation in accordance with feed movement of the wheelhead and electrically connected for control of the feed motor, a positive stop, a rotatable handwheel adapted to engage the positive stop at a predetermined angular position, a control motor connectable to the handwheel to effect rotation thereof towards and away from the positive stop, a synchro transmitter connectable to the handwheel for rotation therewith and electrically connected to the synchro receiver, a cam connectable to the handwheel for rotation therewith and having means for disengagement therefrom for rotatable adjustment relative thereto, means to energize the control motor to rotate the handwheel away from the positive stop and effect feed movement of the wheelhead away from the workpiece, means operable by said cam after a predetermined feed movement in accordance with the rotatable adjustment of the cam to render the control motor ineffective to rotate the handwheel and synchro receiver and to render the rapid advance motor effective to advance the wheelhead in rapid movement toward the workpiece said fixed amount, means responsive to the termination of said rapid feed movement of the wheelhead to render the control motor effective to rotate the handwheel toward the positive stop and effect feed movement of the wheelhead toward the workpiece, and means responsive to engagement of the positive stop by the handwheel to render the rapid advance motor effective to retract the wheelhead said fixed amount.

7. In a grinding machine, a wheelhead having a grinding wheel rotatably mounted therein, a hydraulic wheelhead motor, a drive mechanism mechanically connecting the wheelhead motor to the wheelhead for movement thereof, means defining an electrical signal generator having a rotatable receiver armature and a plurality of rotatable transmitter armatures including a wheelhead position armature, a wheelhead compensation armature, and a wheelhead feed armature, said armatures operable to produce a single control signal output in accordance with the relative positions between the transmitter armatures and the receiver armature, a servo valve electrically connected to the signal generator and responsive to the control signal output therefrom to control the wheelhead motor and move the wheelhead in a direction in accordance with said signal, means responsive to operation of the wheelhead motor to rotate the receiver armature in a direction to reduce said signal control output from the signal generator, an electric position control motor mechanically connected to the position armature, means to produce a predetermined electrical position command signal, means responsive to said electrical position command signal and the instantaneous position of the position armature to energize said position control motor and effect rotation of the position armature to a predetermined angular position, an electric compensation control motor mechanically connected to the compensation armature, means to periodically energize said control motor to effect incremental rotation of said compensation armature to modify the control signal output when said position armature is in said predetermined angular position and compensate for reduction in diameter of the grinding wheel, means responsive to movement of the wheelhead to additionally move said compensation armature in accordance with irregularities in said drive mechanism to compensate therefor, an electric feed control motor selectively connectable to the feed armature, means to energize the feed control motor ineffective to rotate the feed armature after a predetermined rotation thereof, and a handwheel connected to the feed armature to effect manually controlled movement of the wheelhead.

8. In a machine tool the combination comprising a control motor, a first synchro transmitter operatively connected to the control motor for rotation thereby, a control handwheel, a second synchro transmitter operatively connected to the control handwheel for rotation thereby, a machine slide, a slide motor connected to the slide for movement thereof, a synchro receiver mechanically connected for rotation corresponding to movement of the slide by the slide motor and electrically connected to the synchro transmitters for production of an error signal, and means to control the slide motor in response to said error signal.

9. In a grinding machine the combination comprising a control motor, means to control the rate of said motor, a first synchro transmitter operatively connected to the control motor for rotation thereby, a control handwheel, a second synchro transmitter operatively connected to the control handwheel for rotation thereby, a reciprocally movable work table, a table motor connected to the table for movement thereof, a synchro receiver mechanically connected for rotation corresponding to movement of the work table by the table motor and electrically connected to the synchro transmitters for production of an error signal, means to control the table motor in response to said error signal to move the table in accordance with both individual and combined rotation of said control motor and handwheel, and means to reverse the direction of rotation of the first synchro transmitter at preselected spaced positions of the table.

10. In a grinding machine the combination comprising a control motor, means to control the rate of said motor, a first resolver transmitter operatively connected to the control motor for rotation thereby, a control handwheel, a second resolver transmitter operatively connected to the control handwheel for rotation thereby and electrically connected in series with the first resolver transmitter to produce an electric output at one of said resolver transmitters determined by both individual and combined rotation of the control motor and the control handwheel, a reciprocally movable work table, a hydraulic table motor connected to the table for movement thereof, a resolver receiver mechanically connected for rotation corresponding to movement of the work table by the table motor and electrically connected to the output at said one resolver transmitter for production of an error signal, a hydraulic servo-valve responsive to said error signal to control said hydraulic table motor and move the table at a rate and in a direction in accordance with said electric output, and means to reverse the direction of rotation of the control motor at preselected spaced positions of the table.

11. In a machine tool the combination comprising a rotatable synchro transmitter, means operable when actuated to produce a predetermined increment of rotation of the synchro transmitter, a movable cross slide, a synchro receiver mechanically connected for rotation corresponding to movement of the cross slide and electrically connected to the synchro transmitter for production of an error signal, means responsive to the error signal to move the cross slide a predetermined increment on each predetermined rotation of the synchro transmitter, a work table longitudinally reciprocal between reversing points, and means for selected actuation of said synchro transmitter rotating means when the table reaches a reversing point.

12. In a machine tool the combination comprising a movable control member, a control motor connectable to the movable control member for movement thereof, means operable when actuated to energize the control motor for a predetermined amount of rotation to move the control member a predetermined increment, a rotatable synchro transmitter mechanically connected for a predetermined rotation corresponding to the predetermined increment of movement of the control member when the control motor rotates said predetermined amount, a positive stop to terminate movement of the movable control member after

a predetermined total movement thereof, a movable cross slide, a synchro receiver mechanically connected for rotation corresponding to the movement of the cross slide and electrically connected to the synchro transmitter for production of an error signal, means responsive to the error signal to move the cross slide a predetermined increment on each predetermined amount of movement of the control member, a work table, means to reciprocate the work table longitudinally between reversing points, and means for selected actuation of the control motor energizing means when the table reaches a reversing point.

13. In a grinding machine the combination comprising a movable control member, an electric control motor connectable to the movable control member for movement thereof at a predetermined rate, a control timer operable when actuated to energize the control motor for a predetermined period to produce a predetermined increment of movement of the control member, a rotatable synchro transmitter mechanically connected for a predetermined rotation corresponding to the predetermined increment of movement of the control member during said predetermined period, a positive stop to terminate movement of the control member after a predetermined total movement thereof, a movable wheelhead having a grinding wheel rotatably mounted therein, a hydraulic motor connected to the wheelhead; a synchro receiver mechanically connected for rotation corresponding to the movement of the wheelhead by the hydraulic motor and electrically connected to the synchro transmitter for production of an error signal, a hydraulic servo-valve responsive to said error signal to control said hydraulic motor to move the wheelhead a predetermined increment on each predetermined amount of movement of the control member, a work table, means to reciprocate the work table longitudinally between reversing points, and trip operated means for selected actuation of the control timer when the table reaches a reversing point.

14. In a grinding machine the combination comprising a rotatable handwheel, a unidirectional electric control motor, means including a pair of selectively engageable clutches connecting the control motor to the handwheel to move the handwheel in one direction at a predetermined rate when one of said clutches is engaged and to move the handwheel in the opposite direction when the other of said clutches is engaged, said means locking said handwheel when both of said clutches are engaged, a control timer operable when actuated to energize the control motor for a predetermined period to produce a predetermined increment of rotation of the handwheel, means to effect engagement of said one clutch and disengagement of the other clutch during said predetermined period, means to effect engagement of both of said clutches when the control motor is deenergized, a resolver transmitter mechanically connected for a predetermined rotation corresponding to the predetermined increment of rotation of the handwheel during said predetermined period, a positive stop to terminate movement of the handwheel after a predetermined total rotation thereof, a movable wheelhead having a grinding wheel rotatably mounted therein, a hydraulic motor connected to the wheelhead, a resolver receiver mechanically connected for rotation corresponding to the movement of the wheelhead by the hydraulic motor and electrically connected to the resolver transmitter for production of an error signal, a hydraulic servo-valve responsive to said error signal to control said hydraulic motor to move the wheelhead a predetermined increment on each predetermined amount of rotation of the handwheel, a work table, means to reciprocate the work table longitudinally between reversing points, and trip operated means for selected actuation of the control timer when the table reaches a reversing point.

15. In a machine tool the combination comprising a machine slide, a slide motor connected to the slide for movement thereof, a synchro receiver mechanically connected

nected for rotation corresponding to movement of the slide by the slide motor, a position synchro transmitter electrically connected to the synchro receiver for production of a position error signal therefrom, a position control motor operable to rotate said position synchro transmitter, a feed synchro transmitter electrically connected to the synchro receiver for production of a feed error signal therefrom, a feed control motor operable to rotate said feed synchro transmitter, means to render said control motors selectively effective one at a time to rotate said respective synchro transmitters, and means responsive to the error signals from the synchro receiver to control the slide motor.

16. In a machine tool the combination comprising a machine slide, a slide motor connected to the slide for movement thereof, a synchro receiver mechanically connected for rotation corresponding to movement of the slide by the slide motor, a position control motor, a position synchro transmitter operatively connected to the position control motor for rotation thereby and electrically connected to the synchro receiver, means to energize the position control motor to effect rotation of the position synchro transmitter to a predetermined angular position and to produce a position error signal in the synchro receiver, a feed control motor, a feed synchro transmitter operatively connected to the feed control motor for rotation thereby and electrically connected to the synchro receiver, means to energize the feed control motor to effect a predetermined rotation of the feed synchro transmitter at a predetermined rate to produce a feed error signal in the synchro receiver, means to render the feed control motor inoperable when the position control motor is energized, and means responsive to the error signals from the synchro receiver to control the slide motor.

17. In a grinding machine, a wheelhead, a wheelhead motor connected to the wheelhead for movement thereof, a synchro receiver mechanically connected for rotation corresponding to movement of the wheelhead by the wheelhead motor, a position control motor, a position synchro transmitter operatively connected to the position control motor for rotation thereby and electrically connected to the synchro receiver, a set of individually positionable stepping switches operable to produce an electrical output corresponding to a selected angular position of the position synchro transmitter, means connecting said output to the position control motor to effect rotation of the position synchro transmitter to said predetermined angular position to produce a position error signal in the synchro receiver, a feed control motor, a feed synchro transmitter operatively connected to the feed control motor for rotation thereby and electrically connected to the synchro receiver, means to energize the feed control motor to effect a predetermined rotation of the feed synchro transmitter at a predetermined rate to produce a feed error signal in the synchro receiver, means to render the feed control motor inoperable when the position control motor is energized, and means responsive to the error signals from the synchro receiver to control the wheelhead motor.

18. In a grinding machine, a wheelhead having a grinding wheel rotatably mounted therein, a wheelhead motor connected to the wheelhead for movement thereof, a synchro receiver mechanically connected for rotation corresponding to movement of the wheelhead by the wheelhead motor, means responsive to error signals at the synchro receiver to control operation of the wheelhead motor, a position control motor, a position synchro transmitter operatively connected to the position control motor for rotation thereby and electrically connected to the synchro receiver, an information storage mechanism to control operation of the position control motor and synchro transmitter connected thereto to produce position error signals at the synchro receiver, said storage mechanism having a plurality of discrete presettable por-

tions each operable when rendered effective to produce a position error signal at the synchro receiver operable to move the wheelhead to a predetermined position relative to a reference position, a feed control motor, a feed synchro transmitter operatively connected to the feed control motor for rotation thereby and electrically connected to the synchro receiver, means sequentially to render said discrete portions of the position storage mechanism effective to successively position the wheelhead relative to the reference position, and means to control operation of the feed control motor and the synchro transmitter connected thereto to energize said motor after each successive positioning of the wheelhead to produce feed error signals at the synchro receiver and move the wheelhead in a predetermined feed cycle.

19. In a grinding machine, a wheelhead having a grinding wheel rotatably mounted therein, a wheelhead motor connected to the wheelhead for movement thereof, a synchro receiver mechanically connected for rotation corresponding to movement of the wheelhead by the wheelhead motor, means responsive to error signals at the synchro receiver to control operation of the wheelhead motor, a position synchro transmitter electrically connected to the synchro receiver for producing a position error signal therefrom to move the wheelhead an amount corresponding to the amount of rotation of the position synchro transmitter, a position error synchro, a position control motor operable to rotate the position synchro transmitter and the position error synchro, means electrically connecting said control motor to the output of the position error synchro, an information storage mechanism having a plurality of discrete portions each operable when rendered effective to produce an electric command signal in the position error synchro, each of said signals producing an output in the position error synchro in accordance with the command signal and the instantaneous angular position of the position error synchro to run the position control motor and rotate the position synchro transmitter, each of said outputs nulling to stop the control motor when the position control motor has rotated the position synchro transmitter to an angular position determined by the command signal, said rotation of the synchro transmitter effecting positioning movement of the wheelhead, means to render said discrete portions effective to impress each of said command signals on the position error synchro periodically in a predetermined sequence to position the wheelhead periodically in a predetermined sequence of positions, a feed control motor, a feed synchro transmitter operatively connected to the feed control motor for rotation thereby and electrically connected to the synchro receiver, and presettable means to control operation of the feed control motor and the synchro transmitter connected thereto to energize said motor after each successive positioning of the wheelhead to produce feed error signals at the synchro receiver and move the wheelhead in a predetermined feed cycle.

20. In a grinding machine, a wheelhead having a grinding wheel rotatably mounted therein, a wheelhead motor connected to the wheelhead for movement thereof, a synchro receiver mechanically connected for rotation corresponding to movement of the wheelhead by the wheelhead motor, means responsive to error signals at the synchro receiver to control operation of the wheelhead motor, a position synchro transmitter electrically connected to the synchro receiver for producing a position error signal therefrom to move the wheelhead an amount corresponding to the amount of rotation of the position synchro transmitter, a position error synchro, a position control motor operable to rotate the position synchro transmitter and the position error synchro, means electrically connecting said control motor to the output of the position error synchro, an information storage mechanism having a set of stepping switches each having a motor for positioning thereof, said set effective to produce an elec-

tric command signal in the position error synchro to produce an output in the position error synchro in accordance with the command signal and the instantaneous position of the position error synchro to run the position control motor and rotate the position synchro transmitter, said output nulling to stop the position control motor when the position control motor has rotated the position synchro transmitter to an angular position determined by the command signal, said rotation of the synchro transmitter effecting position movement of the wheel head, said position storage mechanism having discrete portions each operable to control said stepping switch motors and thereby position said set of stepping switches when rendered effective, means to render said discrete portions effective periodically in a predetermined sequence, a feed control motor, a feed synchro transmitter operatively connected to the feed control motor for rotation thereby and electrically connected to the synchro receiver, and presettable means to control operation of the feed control motor and the synchro transmitter connected thereto to energize said motor after each successive positioning of the wheelhead to produce feed error signals at the synchro receiver and move the wheelhead in a predetermined feed cycle.

21. In a grinding machine for performing automatically a plurality of operations on a workpiece, the machine having a pair of movable machine members consisting of a wheelhead movable along a path and a table movable transversely to the wheelhead, positioning mechanism for said machine members comprising in combination a wheelhead motor operatively connected to the wheelhead for movement thereof, a table motor operatively connected to the table for movement thereof, two synchro receivers each mechanically connected for rotation corresponding to movement of one of said machine members by the motor connected thereto, two synchro transmitters each connected in circuit with a synchro receiver and operable when rotated relative to the synchro receiver in circuit therewith to produce an error signal in the synchro receiver, means responsive to the error signals produced in the synchro receivers to operate the motors and rotate the synchro receivers in an error signal reducing direction, the motors moving the machine members an amount corresponding to rotation of the respective synchro transmitters, means responsive to a command signal to move each of said synchro transmitters to a predetermined angular position, means to establish successive sets of command signals in a predetermined sequence to successively position the table in a plurality of predetermined positions relative to the wheelhead for grinding different portions of a workpiece and to position the wheelhead a predetermined distance from the table at each of said table positions for determining the diameter of the respective portions of the workpiece, and means to move the wheelhead towards and away from the table in a predetermined feed cycle after said machine members are in said predetermined positions.

22. In a grinding machine having a movable wheelhead with a grinding wheel rotatably mounted therein received on cross ways and a movable work table received on longitudinal ways, the combination comprising an information storage mechanism having discrete portions indexable to render said portions effective one at a time in a predetermined sequence and each operable when effective to produce a wheelhead position command signal and a table position command signal, a wheelhead motor operatively connected to the wheelhead for movement thereof, means responsive to a wheelhead position command signal and the instantaneous position of the wheelhead to operate said motor and effect positioning movement of the wheelhead, a table motor operatively connected to the table for movement thereof, means responsive to a table position command signal and the instantaneous position of the table to operate said motor,

and effect positioning movement of the table, means to operate the wheelhead motor to move the wheelhead through a predetermined grinding cycle after the wheelhead and table have been positioned, and means to index said discrete portions of the information storage mechanism after each grinding cycle.

23. In a grinding machine having a movable wheelhead with a grinding wheel rotatably mounted therein received on cross ways and a work table received on longitudinal ways, the combination comprising, an information storage mechanism having discrete portions indexable to render said portions effective one at a time, each of said portions effective to produce an electrical wheelhead position command signal corresponding to a predetermined position of the grinding wheel cutting surface and an electrical table position command signal corresponding to a predetermined position of the table, a wheelhead motor operatively connected to the wheelhead for movement thereof, an electrical wheelhead position control motor, means to energize the wheelhead position control motor for rotation while the instantaneous position of the grinding wheel cutting surface is spaced from the predetermined position corresponding to the wheelhead command signal, means responsive to rotation of the wheelhead position control motor to operate the wheelhead motor and move the wheelhead to position the grinding wheel cutting surface at the predetermined position corresponding to the wheelhead command signal, an electrical table position control motor, means to energize the table position control motor for rotation while the instantaneous position of the table is spaced from the predetermined position corresponding to the table command signal, means responsive to rotation of the table position control motor to operate the table motor and move the table to the predetermined position corresponding to the table command signal, an electrical wheelhead feed control motor, means to energize said wheelhead feed control motor for rotation after the grinding wheel cutting surface and table are in predetermined positions, preset means to control the rate and amount of said feed control motor rotation, means responsive to movement of the feed control motor to operate the wheelhead motor and produce a grinding cycle, said cycle defined by the controlled rate and amount of rotation of the feed control motor, and means to index said discrete portions of the information storage mechanism after each grinding cycle.

24. In a grinding machine having a movable wheelhead with a grinding wheel rotatably mounted therein received on cross ways and a movable work table received on longitudinal ways, the combination comprising, an information storage mechanism having discrete portions indexable to render said portions effective one at a time, at least one of said portions operable when effective to produce a wheelhead position command signal and two table position command signals, a wheelhead motor operatively connected to the wheelhead for movement thereof, means responsive to a wheelhead position command signal and the instantaneous position of the wheelhead to operate said wheelhead motor and move the wheelhead to a position corresponding to said command signal, a table motor operatively connected to the table for movement thereof, means responsive alternately to the table position command signals and the instantaneous position of the table to operate said table motor and reciprocate the table between predetermined positions corresponding to said table position command signals, means to operate the wheelhead motor to produce an incremental advance of the wheelhead when the table arrives at at least one of said predetermined table positions, and means to index said discrete portions of said information storage mechanism after a preset total of incremental movements of the wheelhead.

25. In a grinding machine having a movable wheelhead with a grinding wheel rotatably mounted therein received on cross ways and a movable work table received

on longitudinal ways, the combination comprising an information storage mechanism having discrete portions indexable to render said portions effective one at a time, at least one of said portions operable when effective to produce an electric wheelhead position signal and two electric table position signals, said storage mechanism including at least three sets of stepping switches having motors, the motors of each switch set operable to position the respective switches thereof in accordance with one of said electric signals, a wheelhead motor operatively connected to the wheelhead for movement thereof, a wheelhead position error synchro electrically connected to the set of switches positioned by the wheelhead position signal to produce a wheelhead position command signal, means operable in response to the wheelhead position command signal and the instantaneous position of the wheelhead to operate said wheelhead motor and move the wheelhead to a position corresponding to said command signal, a table motor operatively connected to the table for movement thereof, a table position error synchro, means alternately to connect electrically said sets of switches positioned by the table position signals to the table position error synchro alternately to produce two different table position command signals therein, and means operable in response to the table position command signal in the table position error synchro and the instantaneous position of the table to move the table to a predetermined position corresponding to said command signal.

26. In a grinding machine having means to support a workpiece, the combination comprising a wheelhead having a rotating grinding wheel mounted therein and movable towards and away from the workpiece, a wheelhead motor operatively connected to the wheelhead for movement thereof, a synchro receiver mechanically connected for rotation corresponding to movement of the wheelhead by the wheelhead motor, a synchro transmitter electrically connected to the synchro receiver for production of an error signal therefrom when the synchro transmitter is rotated relative to the synchro receiver, means to control the wheelhead motor in response to an error signal at the synchro receiver to produce rotation of the synchro receiver in an error signal reducing direction and wheelhead movement corresponding to the amount of rotation of the synchro transmitter, and means to rotate the synchro transmitter a predetermined amount to effect a predetermined movement of the wheelhead toward the workpiece to compensate for grinding wheel attrition.

27. In a grinding machine having means to support a workpiece, the combination comprising a wheelhead having a rotating grinding wheel mounted therein and movable towards and away from the workpiece, a grinding wheel truing tool, means to move the truing tool against the grinding wheel to perform a truing operation, a wheelhead motor operatively connected to the wheelhead for movement thereof, a receiver synchro mechanically connected for rotation corresponding to movement of the wheelhead by the wheelhead motor, a synchro transmitter electrically connected to the synchro receiver for production of an error signal therefrom when the transmitter is rotated relative to the synchro receiver, means to control the wheelhead motor in response to an error signal at the synchro receiver to produce rotation of the synchro receiver in an error signal reducing direction and wheelhead movement corresponding to the amount of rotation of the synchro transmitter, and means to rotate the synchro transmitter a predetermined amount for each truing operation.

28. In a grinding machine, the combination comprising a table having a truing tool mounted thereon, a wheelhead having a rotating grinding wheel mounted therein and movable relative to the table to position the cutting face of the grinding wheel at the truing tool, a wheelhead motor operatively connected to the wheelhead for movement thereof, a receiver synchro mechanically connected

for rotation corresponding to movement of the wheelhead by the wheelhead motor, a synchro transmitter electrically connected to the synchro receiver for production of an error signal therefrom when the synchro transmitter is rotated relative to the synchro receiver, means to control the wheelhead motor in response to an error signal at the synchro receiver to produce rotation of the synchro receiver in an error signal reducing direction and wheelhead movement corresponding to the amount of rotation of the synchro transmitter, means to reciprocate the table to reciprocate the truing tool across the cutting face of the grinding wheel, and means responsive to movement of the table to step the synchro transmitter when the tool is at the end of a pass to move the wheelhead a predetermined amount toward the table.

29. In a grinding machine, a table having a truing tool mounted thereon, a wheelhead having a rotating grinding wheel of predetermined initial diameter mounted therein, a motor connected to the wheelhead for movement thereof towards and away from the table, a synchro receiver mechanically connected for rotation corresponding to movement of the wheelhead by the motor, two synchro transmitters electrically connected to the synchro receiver to jointly produce a single error signal therein, an information storage mechanism having discrete portions effective one at a time, at least two of said portions operable to produce two identical truing position command signals, means to render one of said two portions effective, means responsive to said truing position command signal to rotate one of said synchro transmitters to a predetermined angular position, means to move the wheelhead to a position with the surface of the grinding wheel at the truing tool when said one synchro transmitter is in said predetermined angular position and the other synchro transmitter is in a first predetermined angular position, said means including a servo-valve responsive to an error signal at the synchro receiver to control said motor for movement of the wheelhead and rotation of the synchro receiver in an error reducing direction, means to step said other synchro transmitter to a second predetermined angular position to move the wheelhead toward the table to an adjusted position, means to reciprocate the table to true the grinding wheel, and means to render the other of said discrete portions of the information storage mechanism effective after a predetermined number of grinding operations whereby said first synchro transmitter is rotated to said predetermined angular position and second synchro is in said second predetermined angular position for positioning of the wheelhead at said adjusted position.

30. In a grinding machine, a table having means to support a workpiece on an axis and having a truing diamond mounted on the table at one end of the workpiece a fixed distance from the workpiece axis, a wheelhead having a rotating grinding wheel therein movable towards and away from the table, a positive stop, a feed control member movable relative to the positive stop, means to effect movement of the wheelhead to a predetermined position, means to back the control member a predetermined amount away from the positive stop, means responsive to said movement of the control member to effect movement of the wheelhead away from the table a predetermined feed distance from said predetermined position, a fixed stroke mechanism operatively connected to the wheelhead for rapid movement thereof, means to operate said fixed stroke mechanism after the wheelhead is said predetermined feed distance back from said predetermined position to rapidly advance the wheelhead, means to move the control member back to the positive stop after completion of the rapid advance of the wheelhead to feed the wheelhead into the workpiece said predetermined feed distance, means to reversely operate said fixed stroke mechanism to retract the wheelhead to said predetermined position, means to effect movement of the wheelhead to a reference position for

truing, means to operate said fixed stroke mechanism after the wheelhead is in said reference position to advance the wheelhead to a position with the face of the grinding wheel said fixed distance from the workpiece axis, means to advance the wheelhead a predetermined amount to position the face of the grinding wheel less than said fixed distance from the workpiece axis, and means to effect relative reciprocation between the truing tool and the wheelhead to true the grinding wheel to produce a sharp face at said fixed distance from the workpiece axis.

31. In a grinding machine, a wheelhead having a grinding wheel rotatably mounted therein, said grinding wheel having a previously trued radius, a table having a truing tool mounted thereon for movement along a path as the table reciprocates, a fixed stroke motor operatively connected to the wheelhead for rapid advance and retraction thereof a fixed distance, a wheelhead motor operatively connected to the wheelhead, a synchro receiver operatively connected to the wheelhead motor for rotation in accordance with movement of the wheelhead by the wheelhead motor, a servo valve operable in response to an error signal at the synchro receiver to operate the wheelhead motor for movement of the wheelhead and rotation of the synchro receiver in an error reducing direction, a first synchro transmitter electrically connected to the synchro receiver, a second synchro transmitter electrically connected to the synchro receiver and having a stepping motor connected thereto for incremental rotation through a succession of angular positions, means to rotate said first synchro transmitter to a predetermined angular position to produce an error signal in the synchro receiver for positioning the wheelhead in a reference position with the previously trued radius of the grinding wheel said fixed distance from the path of the truing tool, said error signal determined by said angular position of the first synchro transmitter, the angular position of said second synchro transmitter, and the instantaneous position of the synchro receiver whereby said reference position is determined by the angular positions of the first and second synchro transmitters, means to actuate said rapid advance motor to advance the previously trued radius of the grinding wheel to the path of the truing tool, means to actuate said stepping motor to effect incremental rotation of the second synchro transmitter and thereby effect incremental advance of the grinding wheel into the path of the truing tool, means to reciprocate the table to reduce the radius of the grinding wheel from the previously trued radius an amount equal to said incremental movement of the wheelhead effected by the incremental rotation of the second synchro transmitter, and means to reversely operate said fixed stroke mechanism to retract the wheelhead to an adjusted reference position spaced forwardly from said reference position a distance equal to the difference between the new radius and the previously trued radius whereby the next subsequent positioning of the first synchro transmitter in said predetermined angular position will position the wheelhead in said adjusted reference position with the newly trued radius of the grinding wheel said fixed distance from the path of the truing tool.

32. In a grinding machine for performing a grind on each of a plurality of portions of a workpiece, the combination comprising, a table having means to support a workpiece on an axis and having a truing diamond mounted on the table at one end of the workpiece a fixed distance from the workpiece axis, a wheelhead having a rotating grinding wheel therein movable towards and away from the table, means to produce a series of sets of command signals, one set effective at a time and said sets effective in a predetermined sequence, said sets including an operating set having a wheelhead operating position command signal and a table operating position signal, and at least one truing set having a wheelhead truing position command signal and a table truing position command signal, a positive stop, a feed control member movable

relative to and adapted to engage said positive stop, means including a wheelhead position control motor to effect positioning movement of the wheelhead, said wheelhead position control motor responsive to a wheelhead operating position command signal to move the wheelhead to an operating position when an operating command set is effective and said wheelhead position control motor responsive to a wheelhead truing position command signal to move the wheelhead to a reference position when a truing command set is effective, means including a table control motor to effect positioning movement of the table, said table control motor responsive to a table operating position command signal to move the table to an operating position when an operating command set is effective and said table control motor responsive to a table truing position command signal to move the table to position the diamond adjacent the grinding wheel when a truing command set is effective, means to effect movement of the control member a predetermined amount back away from the positive stop after the wheelhead is in an operating position, means responsive to said movement of the control member to effect movement of the wheelhead away from the table a predetermined feed distance from said operating position, a fixed stroke mechanism operatively connected to the wheelhead for rapid movement thereof, means to operate said fixed stroke mechanism after the wheelhead is said predetermined feed distance back from the operating position to rapidly advance the wheelhead, means to effect movement of the control member back to the positive stop after completion of the rapid advance of the wheelhead to feed the wheelhead into the workpiece said predetermined feed distance, means to reverse operate said fixed stroke mechanism to retract the wheelhead to the operating position corresponding to the command signal, means to operate said fixed stroke mechanism after the wheelhead is in the reference position to advance the grinding wheel to the truing diamond, means to advance the wheelhead toward the diamond a predetermined amount and modify the effect of the command signal on the wheelhead positioning means a corresponding amount, and means to effect reciprocation of the table and the diamond mounted thereon after the wheelhead has been advanced said predetermined amount.

33. In a grinding machine for performing a grind on each of a plurality of portions of a workpiece, the combination comprising, a table having means to support a workpiece on an axis and having a truing diamond mounted on the table at one end of the workpiece a fixed distance from the workpiece axis, a wheelhead having a rotating grinding wheel therein movable towards and away from the table, means to produce a series of sets of command signals one at a time, some of said sets including a wheelhead operating position command signal and two table operating position command signals, and at least one of said sets including a wheelhead truing position command signal and two table truing position command signals, a position synchro member, a feed synchro member, and a truing synchro member, said synchro members connected in circuit, means responsive to rotation of each synchro member to move the wheelhead, a positive stop, a feed control member movable relative to and adapted to engage said positive stop, said feed control member operatively connected to said feed synchro member for rotation thereof, means responsive to a wheelhead operating position command signal to rotate the position synchro member to a predetermined angular position to position the cutting surface of the grinding wheel a predetermined distance from the axis of the workpiece and responsive to a wheelhead truing position command signal to position the cutting surface a predetermined reference distance from the axis, means responsive to a pair of table operating position command signals to reciprocate the table between positions cor-

responding to said command signals and responsive to a pair of table truing command signals to reciprocate the diamond at the grinding wheel, means to effect movement of the control member a predetermined amount back away from the positive stop to back the wheelhead a predetermined feed amount from an operating position, a fixed stroke mechanism operatively connected to the wheelhead for rapid movement thereof, means to operate said fixed stroke mechanism after the wheelhead has been backed by the control member from an operating position to rapidly advance the wheelhead, means responsive to the reciprocation of the table between operating positions to effect incremental movement of the control member back to the positive stop after completion of the rapid advance of the wheelhead to feed the wheelhead into the reciprocating workpiece in increments totaling said predetermined feed amount, means to reversely operate said fixed stroke mechanism to retract the wheelhead to the operating position, and means to rotate said truing synchro member a predetermined amount after the position synchro member and the table have been operated in response to the truing command signals to true the grinding wheel and compensate for grinding wheel attrition.

34. In a machine tool having a slide member mounted on a base member, the combination of a slide motor, a drive mechanism connected between the slide and the slide motor, means to produce a predetermined electrical signal, means responsive to said signal and the instantaneous position of the slide to produce an error signal, means responsive to said error signal to control the slide motor for movement of the slide in an error reducing direction, a cam connected to one of said members having a cam face formed in accordance with irregularities in the drive mechanism, a cam follower connected to the other of said members adapted to engage the cam for movement in accordance with the conformation thereof as the slide member moves on the base member, and an electrical element having a movable member connected to the cam follower and operable to alter said error signal in accordance with movement of the cam follower.

35. In a grinding machine having means to support a workpiece, a wheelhead having a rotating grinding wheel mounted therein and movable towards and away from the workpiece, a wheelhead motor, a wheelhead drive mechanism connected between the wheelhead motor and the wheelhead, a synchro receiver mechanically connected for rotation corresponding to movement of the wheelhead by the wheelhead motor, means to control the wheelhead motor in response to an error signal at the synchro receiver to produce movement of the wheelhead and rotation of the synchro receiver in an error signal reducing direction, means to produce an error signal at the synchro receiver, a synchro transmitter electrically connected to the synchro receiver for modification of said error signal therefrom when the synchro transmitter is rotated relative to the synchro receiver, means to rotate the synchro transmitter in accordance with inaccuracies in the drive mechanism to effect corrective compensation therefor in movement of the wheelhead.

36. In a grinding machine having a base and having means on the base to support a workpiece, a wheelhead having a rotating grinding wheel mounted therein, said wheelhead mounted on the base and movable towards and away from the workpiece, a wheelhead motor, a wheelhead drive mechanism connected between the wheelhead motor and the wheelhead, a synchro receiver mechanically connected for rotation corresponding to movement of the wheelhead by the wheelhead motor, means to control the wheelhead motor in response to an error signal at the synchro receiver to produce movement of the wheelhead and rotation of the synchro receiver in an error signal reducing direction, means to produce an error signal at the synchro receiver, a synchro transmitter electrically connected to the synchro receiver for modification

of said error signal therefrom when the synchro transmitter is rotated relative to the synchro receiver, a compensating cam member having a cam surface shaped in accordance with inaccuracies in the drive mechanism, a compensating cam follower member engaged with said cam surface and operatively connected to the synchro transmitter to effect rotation thereof when there is relative movement between the compensating cam member and the compensating cam follower member, means connecting one of said compensating members to the base, and means connecting the other of said compensating members to the wheelhead.

37. In a grinding machine having a base and having means on the base to support a workpiece, a wheelhead having a rotating grinding wheel mounted therein, said wheelhead mounted on the base and movable towards and away from the workpiece, a wheelhead motor, a wheelhead drive mechanism connected between the wheelhead motor and the wheelhead, a synchro receiver mechanically connected for rotation corresponding to movement of the wheelhead by the wheelhead motor, means to control the wheelhead motor in response to an error signal at the synchro receiver to produce movement of the wheelhead and rotation of the synchro receiver in an error signal reducing direction, means to produce an error signal at the synchro receiver, a synchro transmitter electrically connected to the synchro receiver for modification of said error signal therefrom when the synchro transmitter is rotated relative to the synchro receiver, a compensating cam member having a cam surface shaped in accordance with inaccuracies in the drive mechanism, a compensating cam follower member engaged with said cam surface and movable in response to changes in shape of the cam surface when said compensating cam member and compensating cam follower member are relatively moved, means connecting one of said compensating members to the base, means connecting the other of said compensating members to the wheelhead, means to produce a predetermined rotation of the synchro transmitter to effect a predetermined movement of the wheelhead, and means to effect a corrective rotation of the synchro transmitter in response to movement of the compensating cam follower member.

38. In a grinding machine having a base and means on the base to support a workpiece, a wheelhead having a rotating grinding wheel mounted therein, said wheelhead mounted on the base and movable towards and away from the workpiece, a wheelhead motor, a wheelhead drive mechanism connected between the wheelhead motor and the wheelhead, a synchro receiver mechanically connected for rotation corresponding to movement of the wheelhead by the wheelhead motor, means to control the wheelhead motor in response to an error signal at the synchro receiver to produce movement of the wheelhead and rotation of the synchro receiver in an error signal reducing direction, means to produce an error signal at the synchro receiver, a synchro transmitter electrically connected to the synchro receiver for modification of said error signal therefrom when the synchro transmitter is rotated relative to the synchro receiver, a compensating cam member having a cam surface shaped in accordance with inaccuracies in the drive mechanism, a compensating cam follower member engaged with said cam surface and movable in response to changes in shape of the cam surface when said compensating cam member and compensating cam follower are relatively moved, means connecting one of said compensating members to the base, means connecting the other of said compensating members to the wheelhead, a pinion member mounted for rotation about an axis and operatively engaged with the synchro transmitter to effect rotation thereof when the pinion is rotated, a synchro transmitter support member adapted to rotatably receive the transmitter synchro and mounted for rotation about the pinion axis to effect rotation of the synchro transmitter when the support

member is rotated, means responsive to the movement of the cam follower member to effect rotation of one of said synchro transmitter rotating members, and means to effect predetermined rotation of the other of said synchro transmitter rotating members.

39. In a grinding machine having a base and means on the base to support a workpiece, a wheelhead having a rotating grinding wheel mounted therein, said wheelhead mounted on the base and movable towards and away from the workpiece, a wheelhead motor, a wheelhead drive mechanism connected between the wheelhead motor and the wheelhead, a synchro receiver mechanically connected for rotation corresponding to movement of the wheelhead by the wheelhead motor, means to control the wheelhead motor in response to an error signal at the synchro receiver to produce movement of the wheelhead and rotation of the synchro receiver in an error signal reducing direction, means including a first synchro transmitter electrically connected to the synchro receiver to produce an error signal at the synchro receiver, a second synchro transmitter electrically connected to the synchro receiver for modification of said error signal therefrom when the second synchro transmitter is rotated relative to the synchro receiver, a compensating cam member having a cam surface shaped in accordance with inaccuracies in the drive mechanism, a compensating cam follower member having a rack portion and engaged with said cam surface for movement in response to changes in shape of the cam surface when said compensating cam member and said compensating cam follower member are relatively moved, means connecting one of said compensating members to the base, means connecting the other of said compensating members to the wheelhead, a gear segment mounted for pivotal movement about an axis and engaged with said rack portion, said gear segment adapted to rotatably receive said second synchro transmitter, a pinion mounted on the gear segment pivot axis, a gear connected to the second synchro transmitter and engaged with said pinion for rotation of the second synchro transmitter in response to movement of the rack portion, and a stepping motor operatively connected to the pinion for predetermined incremental rotation thereof relative to the gear segment.
40. In a grinding machine, a wheelhead having a grinding wheel therein, a hydraulic wheelhead motor mechanically connected to the wheelhead for movement thereof, means defining an electric signal generator having a plurality of movable members to produce a single control signal output, a servo-valve electrically connected to the signal generator and responsive to the control signal output therefrom to control the wheelhead motor and move the wheelhead in a direction in accordance with said signal, means responsive to movement of the wheelhead to reduce said control signal output from the signal generator, means to move one of said movable members in the signal generator to a predetermined position to produce a control signal output and effect positioning movement of the wheelhead, means to move another of said movable members in the signal generator an amount corresponding to reduction of the grinding wheel to modify said control signal output and modify positioning movement of the wheelhead, and means to move yet another of said movable members in the signal generator a predetermined amount after the wheelhead is in position to effect a predetermined feed movement of the wheelhead.
41. In a grinding machine, a wheelhead having a grinding wheel rotatably mounted therein, a hydraulic wheelhead motor mechanically connected to the wheelhead for movement thereof, means defining an electric signal generator having a plurality of movable armatures responsive to mechanical command signals to produce a single control output, a servo valve electrically connected to the signal generator and responsive to the con-
- 70

trol signal output therefrom to control the wheelhead motor and move the wheelhead in a direction in accordance with said signal, means responsive to movement of the wheelhead to reduce said control signal output from the signal generator, a position control motor mechanically connected to one of said armatures for movement thereof to a predetermined position to produce a control signal output and effect positioning movement of the wheelhead, a compensation control motor mechanically connected to another of said armatures for movement thereof an amount corresponding to reduction of the grinding wheel to modify the position assumed by the wheelhead when said one armature is in said predetermined position, and a feed control motor mechanically connected to yet another of said armatures for movement thereof a predetermined amount after the wheelhead has assumed said predetermined modified position to effect a predetermined feed movement of the wheelhead.

42. In a grinding machine, a wheelhead having a grinding wheel rotatably mounted therein, a hydraulic wheelhead motor mechanically connected to the wheelhead for movement thereof, means defining an electric signal generator having a plurality of rotatable armatures including a wheelhead position armature, a wheelhead compensation armature, and a wheelhead feed armature, said armatures responsive to mechanical command signals to produce a single control signal output, a servo-valve electrically connected to the signal generator and responsive to the control signal output therefrom to control the wheelhead motor and move the wheelhead in a direction in accordance with said signal, means responsive to movement of the wheelhead to reduce said control signal

output from the signal generator, an electric position control motor mechanically connected to the position armature to produce a mechanical position command signal, means to produce a predetermined electrical position command signal, means responsive to said electrical position command signal and the instantaneous position of the position armature to energize said position control motor and effect rotation of the position armature to a predetermined angular position to produce a control signal output and effect positioning movement of the wheelhead, an electric compensation control motor mechanically connected to the compensation armature to produce a mechanical compensation command signal, means to periodically energize said control motor and effect incremental rotation of said compensation armature to modify the control signal output when said position armature is in said predetermined angular position and modify the position assumed by the wheelhead, an electric feed control motor mechanically connected to the feed armature to produce a mechanical feed command signal, means to energize said feed control motor after the wheelhead is in said modified position to produce rotation thereof through a predetermined angle and effect feed movement of the wheelhead a predetermined distance, and a hand-wheel mechanically connected to one of said armatures to effect desired movement of the wheelhead thereby.
